UNITED STATES PATENT OFFICE.

CHARLES L. GOODRUM, OF ROCHESTER, NEW YORK, ASSIGNOR, BY MESNE ASSIGNMENTS, TO WESTERN ELECTRIC COMPANY, INCORPORATED, A CORPORATION OF NEW YORK.

AUTOMATIC TELEPHONE SYSTEM.

1,247,395.

Specification of Letters Patent. Patented Nov. 20, 1917.

Application filed May 4, 1907. Serial No. 371,843.

To all whom it may concern:

Be it known that I, CHARLES L. GOODRUM, of Rochester, in the county of Monroe and State of New York, have invented certain new and useful Improvements in Automatic Telephone Systems; and I do hereby declare the following to be a full, clear, and exact description of the same, reference being had to the accompanying drawings, forming a part of the specification, and to the reference-numerals marked thereon.

My present invention relates to automatic telephone systems, and it has for its primary object to provide an improved system in which the talking and signaling operations between different subscribers' stations, and the apparatus for connecting different telephone lines, at the central office or exchange, may all be effected over a full metallic circuit comprising but two wires without grounded connections.

Another object of the invention is to provide means for connecting different telephone lines at the central office or exchange comprising generally a finder switch and an associate connector switch, both serving a plurality of lines, the former operating automatically to select a line on which a call originates and extend it to the connector switch which latter is responsive to impulses of current on the calling line and serves to connect it to a particular outgoing line on which it is desired to call a subscriber, the signaling of said called subscriber being accomplished automatically.

In addition to the above described attainments of the invention it also comprehends the employment of two or more finder switches, the movable elements of which travel in opposite directions, or move in the same direction to coöperate with equivalent sets of line or instrument circuit terminals, arranged in reverse positions in the banks of contacts on the two switches, whereby one of them will pick up the incoming line in advance of the other. The arrangement of these parts of the apparatus has this additional function; that should the first switch fail to make the connection, the line will be subsequently picked up by the second finder switch, when its

movable elements engage its respective terminals of said line.

The arrangement of the parts of the apparatus embodying this invention permits another object to be obtained; namely; the location of an incandescent lamp at each subscriber's instrument which is lighted by current in the instrument circuit supplied from the central office or exchange, when said circuit is closed. The lighting of this lamp as soon as a subscriber removes his receiver, illuminates the dial of the impulse transmitter and facilitates the subscriber's labor in sending in a call.

To these and other ends the invention consists in certain improvements and combinations of parts all as will be hereinafter fully described, the novel features being pointed out in the claims at the end of the specification.

In the drawings:

Figures 1 and 2 are diagrammatic views illustrating generically the line connection as it is effected between two instrument circuits by means of the finder and connector switches, the operating mechanism of the switches being omitted, the first view showing the positions of the switches in connecting instrument A with instrument B and the second illustrating the reverse connection.

Fig. 3 is a plan view illustrating a type of switch which may be employed as finder and connector switches for operation with this system.

Figs. 4 and 5 are detail sectional views thereof taken on the lines 4*-4* and 5*-5* respectively.

Fig. 6 is a diagrammatic view illustrating a finder switch in conjunction with an instrument circuit, including that part of the switch controlling mechanism which automatically extends said circuit to the connector switch, and

Fig. 7 is a similar view of the connector switch showing the controlling mechanism by means of which the switch connects an incoming line or circuit, on which a call is originated, to another outgoing line.

Fig. 8 is an enlarged diagrammatic detail view of the devices for operating the con-

ector switch illustrating the operation of the mechanism for setting up a connection and subsequently restoring the switch to its normal position.

5 Fig. 9 is a diagrammatic illustration of the apparatus associated with that shown in Figs. 7 and 8 for automatically operating the calling devices on the various outgoing lines or circuits intermittently which is ar-
10 rested when the called subscriber answers his signal.

Fig. 10 is a diagrammatic view showing 15 duplicate arrangement of the associated finder and connector switches shown in Figs. 6 and 7.

Similar reference numerals in the several figures indicate similar parts.

In a telephone exchange system embodying my invention the connections between 20 different telephone lines are automatically set up or effected by apparatus arranged at the central office or exchange, and the telephone lines or circuits are divided into two classes comprising, first, incoming lines or 25 those on which calls are originated, by subscribers who desire to establish communication with other parties, and, secondly, outgoing lines over which the calls are despatched to signal said parties. Each line 30 may, at different times, be of either class and it will therefore be understood when these lines are referred to in the following description, that an incoming line or circuit is one leading from a subscriber's telephone 35 or station over which impulses of current are sent to connect said line to an outgoing line and that the latter is the one on which the signaling devices are actuated when the connection has been set up or completed be-
40 tween the telephone instruments of the calling and the called subscribers.

In the system embodying the present invention it is possible to connect through the central office or exchange apparatus a given 45 line with any other line and to this end all the lines lead to terminals on a finder switch, or a plurality of such switches, and to similar terminals on an associate connector switch or switches. The finder switch per-
50 forms the function of selecting an incoming line on which a call has been originated, and the connector switch performs a similar function in selecting the outgoing line leading to a particular telephone instrument, or 55 subscriber's station, with which the calling subscriber desires to communicate. The movable elements or wipers of the finder and connector switches are connected, or tied together, so that when the functions of 60 each have been performed, the talking circuit, from the incoming to the outgoing line, is extended through them and may be retained until one of the two communicating subscribers desires to effect the discon-
65 nection of said lines.

In Figs. 1 and 2 the above described connections are shown diagrammatically, two separate instruments being shown in each, and indicated generally by A and B, with a single finder switch F and a single connector switch C. In Fig. 1, the movable elements or wipers of the two switches are shown in position to illustrate the connection established from instrument A to instrument B when the circuit of the first mentioned instrument is the incoming line on which a call is originated, and in Fig. 2 these parts of the switches are shown in the position which they occupy when instrument B is the one on which a call was initiated.

The telephone instruments may be of the usual or any preferred construction comprising generally a transmitter 1, a receiver 2, and the signaling devices or bells 85 3, all of which are arranged in the circuit of the line wires A'-A² of instrument A, and B'-B² of instrument B. The instrument circuits are normally open at each subscriber's station at the contacts A³-B³ 90 which are controlled by the receiver hook and are closed when the latter is released by the subscriber removing his receiver therefrom. Each pair of wires constituting the circuits of the telephone instruments is extended to 95 the aforementioned switches located at the central office and terminate in immutable contacts located thereon, those of the wires A'-A² being located on the switch F, as indicated by A¹⁰-A²⁰, the corresponding 100 contacts on the switch C being indicated by A¹¹-A²¹ said contacts being tied together by conductors A¹²-A¹³, the similar contacts of the wires B'-B² on the switch F are indicated by B¹⁰-B²⁰ and on the switch C 105 by B¹¹-B²¹, said pairs of contacts being also tied together by wires B¹²-B¹³. The operating mechanisms controlling the movable elements or wipers of the two switches have been omitted from these illustrations 110 but as will appear more fully hereinafter, they are designed to cause such switches to move progressively over a bank of contacts or terminals, representing a large number of telephone lines. The wipers of the switch F 115 are indicated by F'-F² and those of the switch C by C'-C², the corresponding wipers of the two switches being connected by wires 4 and 5. From an inspection of Fig. 1 it will be seen that the complete circuit between the instruments A and B is traced as follows: instrument A wire A', contact A¹⁰, wiper F', wire 5, wiper C², contact B¹¹, wire B', instrument B, wire B², contact B²¹, wiper C', wire 4, wiper F', contact A²⁰, wire A², instrument A. The foregoing is predicated upon the fact that the call originated at the instrument A and the mechanism of the finder switch operated to pick up the contacts of the incoming cir- 130

cuit A'-A² after which the switch C was actuated to connect said circuit with the terminals of the outgoing line B'-B².

Supposing a reverse operation to be effected in a like manner. The movable elements of the finder switch F first traverses its bank of contacts or terminals, until reaching the terminals B¹⁰-B²⁰ of the line B'-B² then the connector switch C operates to pick up the terminals A¹¹-A²¹ of the line A'-A². The circuit between the two telephone instruments will then be traced as follows: instrument B, wires B², B¹⁹, contact B²⁰, wiper F', wire 4, wiper C', contact A²¹, wires A¹⁸, A², instrument A, wires A', A¹², contact A¹¹, wiper C², wire 5, wiper F², contact B¹⁰, wires B¹², B', instrument B.

The switches.

In illustrating the mechanism by means of which the connections between the lines is effected, a type of switch adapted for this purpose is shown in Fig. 3, details thereof being shown in Figs. 4 and 5. This switch is capable of performing the functions of either the finder or connector switch, and comprises generally a progressively movable member 6, which is adapted to be advanced step by step, and to this end is made circular in form and is mounted upon a revolvable shaft 7 journaled at its lower end in the base plate 8, and supported at its upper end by a bearing on a bracket 9, the ends of which extend downwardly and are secured to the base plate, as shown in Fig. 5. Carried on the movable member and insulated therefrom are contact elements or spring wipers 10 and 11, corresponding to the wipers F'-F² of the switch F and C'-C² of the switch C. These elements are arranged one below the other and their outer ends are adapted to coöperate with a series of insulated terminal contacts 12 and 13, arranged in pairs corresponding to the contacts A¹⁰-A²⁰, etc., those of each pair being located in vertical alinement as shown in Fig. 4. As each switch controls a plurality of telephone lines, these pairs of terminals are supported upon a segmental bridge 14, and are arranged concentric with the center of movement of the wipers. Beneath said contacts are other contacts 15 and 16 with which coöperate wipers 17 and 18, the purpose of all of which will be subsequently described, but it may be here stated that the usual terminal contacts 12, 13 and 15 and 16 are arranged in sets, each set being devoted to a single incoming instrument circuit. The rear end of each wiper is provided with a segment, as indicated by 10^a, 11^a, 17^a, 18^a, with which coöperate brushes 10^b, 11^b, 17^b, 18^b, supported in a holder 19, of insulating material, secured to one of the ends of the bracket 9. Connected to the lower end of

the shaft 7 is a coil spring 20 to which sufficient tension is applied to return the shaft and the parts supported thereon to the normal position, shown in Fig. 3, when they are released.

The means for operating the movable element comprises a pawl 21; pivoted to the upper end of an arm 22 on which it is moved by a spring 23 into engagement with teeth 24 on the periphery of the element 6. The arm 22 is pivoted at the point 25 and is provided with a laterally extending end 26, forming an armature which coöperates with the motor magnet 27, employed for actuating the operating devices, said armature being normally held in retracted position by the spring 28 bearing against the stud 29 on the arm 22, which also serves to advance the member 6 when the pawl 21 is in engagement therewith. A spring operated pawl 30 serves to lock the movable element in adjusted position and at its outer end is a finger 31, projecting beneath the end of the pawl 21, the arrangement of the parts being such that when the pawl is moved downwardly into an inoperative position the detent will be retracted, as shown in Fig. 3. The means for effecting the release of the member 6 comprises a spring latch member 33 having an end 34 which is adapted to hook over the edge of a lip 32 depending from the pawl 21. At its lower end the spring 33 is attached to an armature 35 pivotally supported in proximity to the release magnet 36 and carrying an upwardly extending arm 37 provided with a stud 38 with which coöperates a spring 39 normally tending to move it in a direction to retract the armature 35. Supported upon the base plate 8, in front of the spring 33, is a stud 40, which limits the lateral movement of the spring when the armature 35 is retracted, thereby permitting the lip 32, of the pawl to be disengaged from the hooked end of the spring when said pawl has been retracted by the energizing of the motor magnet 27. The movable member, 6, controls two circuits, as will be further described in connection with the diagrammatic illustrations, which include a contact spring 41 playing between contact members 42 and 43, supported in a holder 44, on the base plate 8. The spring 41 has a normal tendency to engage the contact 42, but is held in engagement with the contact 43, when the member 6 and the contact elements carried thereon are in their normal position, by a pin 45 mounted on the member, which releases said spring upon the first step or movement imparted thereto.

The finder and connector switches are actuated by electromagnetic devices peculiar to each, those of the finder switch being automatically set into operation, and controlled by secondary circuits, which are es-

tablished when an instrument circuit is closed at the subscriber's station, and the mechanism of the connector switch is rendered operative when the finder switch has 5 picked up the incoming or calling circuit and is controlled by impulses of current which may be despatched by a suitable form of impulse transmitter located at the subscriber's station, to select a given outgoing 10 line, or called circuit. Accordingly the instrument circuit, comprising wires A'—A², is extended, as indicated at A¹⁴—A²⁴, Figs. 1, 2 and 6, to normally closed contacts A⁴¹—A⁴², one of which is mounted upon a 15 spring finger provided with an end 46 adapted to coöperate with teeth of an impulse transmitter A⁴ which may be rotated to separate said contacts and thereby transmit or send over the operating circuit one or 20 more impulses of current, when the circuit is closed at the hook contacts A³.

The electromagnetic mechanisms for causing the various switches to perform their respective functions, are all adapted to be 25 operated from a common battery Z, Figs. 7 and 8, but in order to facilitate the description and illustration, and render a more comprehensive understanding of the various circuits to be had, these are shown in 30 the diagrammatic views as receiving current from different sources or sets of batteries, Z'—Z², etc. The circuits in many instances, are shown with the conventional ground or earth connections, but it will be understood 35 that where the term ground is employed and shown, it refers to a connection leading directly to one side of the main battery, so that a telephone system embodying this invention, when installed in working order, is 40 entirely free of the so-called grounds employed for actuating parts of the apparatus, thereby eliminating line disturbances or other troubles attributable to this cause.

45 *The finder switch.*

Associated with each telephone line or instrument circuit, is an actuating relay A⁵, which is energized when the instrument circuit is closed to actuate the operating mechanism of the finder switch F, and a cut-off relay A⁶, the function of which is to restore 50 the actuating relay to normal position when the finder switch has picked up its corresponding instrument circuit. In Fig. 6 the 55 finder switch is shown provided with a plurality of sets of the four terminal contacts which are arranged in rows, as illustrated in Fig. 4, those constituting the lower pair of the set related to the circuit of instrument 60 A being indicated by f¹⁵—f¹⁶. Leading from the contact f¹⁵ is a wire A¹⁶, connected to one end of the coil of the cut-off relay A⁶, the other terminal thereof being supplied at certain times with current from the battery 65 Z'; another wire A¹⁵ leads from the contact

f¹⁶ to a back contact a¹⁵, with which the armature a⁵ of the actuating relay normally engages, said armature having a grounded connection, z⁴. One end of the coil of the actuating relay A⁵ is connected to the battery Z² and its other extremity is connected by the wire a' to a back contact a² with which normally engages the armature a⁶, of the cut-off relay, said armature being connected with one side of the instrument 70 circuit by the wire a³, joined to the line wire A². A second armature controlled by the cut-off relay, indicated by a⁴, is connected by a wire a⁷ which is joined to the other wire A' of the instrument circuit. This 75 armature normally engages a back contact a⁸ which has a grounded connection, z². In Fig. 7 corresponding parts to those just described are found illustrated in connection with the instrument B, said parts being indicated by the use of the letters B, b, with the appropriate exponents, reference to which will be made hereafter in explaining the operation of certain parts of the apparatus. 80

It has been explained, in connection with Figs. 3, 4 and 5, how the movable contact elements coöperate with the several terminals in the bank of contacts of each switch, but in Figs. 6 and 7 the illustrations are 85 simplified by showing the circuit wires connected directly to the wipers, whereas, in reality they are connected to brushes, such as 10^b, 11^b, 17^b, 18, shown in Fig. 5. Referring now particularly to Fig. 6, it will be seen 90 that the brushes F'—F² are extended by the wires 4^A and 5^A through normally closed contacts on the armatures of two relays F³—F⁴, which will be described more fully hereinafter, the function ascribed to the 95 former being that of opening the extended instrument circuit over the wires 4 and 5, during the rotation of the brushes of the finder switch F, when moving in one direction to pick up an incoming line, while that 100 of the latter relay is to open said circuit during the movement of these parts when returning in the opposite direction to their normal position. The opening of the ties between the switches eliminates any vibration 105 in the receiver of a subscriber's telephone when a plurality of switches are employed for the purpose of handling two or more incoming calls simultaneously, and it 110 also prevents any possible interference with the connector switch mechanism during the retrograde movement of the parts of the 115 finder switch. 120

Operating conjointly with the motor and release magnets, 27^F and 36^F respectively, is 125 a relay F⁵ which performs dual functions, namely: the completing of a secondary circuit of the motor magnet 27^F, over which current is supplied to cause its continuous 130 operation until the wipers of the switch F

have picked up the incoming line, and to close another circuit by means of which the cut-off relay A^6 of said line is energized when its terminals have been found by the 5 finder switch. The motor magnet 27^F , the relay F^5 and the line opening relay F^3 are connected in parallel by the wires $f-f'$ but as the relay F^3 will be referred to more fully hereinafter, it may be disregarded at this 10 point and the wire f' considered as grounded or connected to one terminal of the battery Z^3 which supplies current to the starting circuit controlled by the armature a^5 of the actuating relay A^5 . Connected to one end 15 of the coil of the motor magnet 27^F is the battery Z^4 , the other end of said coil being connected by the wire f^2 to the armature f^3 of the motor magnet, which normally engages the back contact f^4 of the wire f . The 20 latter is also joined to the contact f^{43} with which the spring controlled switch arm f^{41} normally engages, the latter being connected by the wire f^5 to the front contact f^6 which is engaged by the armature a^5 when the latter is attracted by the actuating relay A^5 . 25 The other contact with which the switch arm f^{41} coöperates, is indicated by f^{42} , and this has a ground connection, z^5 over which current is transmitted at certain times to permit the finder switch to be restored. The 30 third wiper, f^{17} is connected by the wire f^8 to an armature f^9 on the relay F^6 normally resting against a back contact f^{10} , which is connected by the wire f^{11} , to a ground z^1 , over which current may be received from 35 the battery Z' to energize the cut-off relay A^6 , when the brush f^{17} engages the contact f^{15} . The fourth brush f^{18} is connected by the wire f^{12} to an armature f^{13} , adapted to normally coöperate with a back contact f^{14} connected by a wire f^{15} to ground. This armature, f^{13} is also arranged on the relay F^5 , and when the latter is energized it is moved into 40 engagement with the contact f^{10} , connected by the wire f^{20} to the wire f .

The foregoing description has been confined to the parts of a single telephone circuit but it will be understood that the finder switch F serves a comparatively large number 45 of such circuits, each of which has associated with it the previously described actuating and cut-off relays. The line wires A' , A^2 and the local wires A^{15} and A^{16} of the several telephone circuits, are connected to the respective terminals of each tier in the bank of contacts (such as those indicated by 12, 13, 15 and 16 in Fig. 4).

All of the instrument circuits when not in use, are normally open at the receiver hook 50 contacts A^3 , and as the brushes of the finder switch, under such condition, are in inoperative condition, the spring switch f^{41} is retained in engagement with its back contact f^{43} .

55 In order to facilitate an understanding of

the movement of the finder switch, an additional telephone instrument has been illustrated in Fig. 6, which is indicated by D . This subscriber's set comprises the actuating relay D^5 operating the armature d^5 , 70 which is grounded at z^{14} and coöperates with the back contact d^{150} connected by the local wire D^{15} to the terminal d^{16} on the switch F . The cut-off relay of this set is indicated by D^6 , the circuit of which includes the wire D^{16} , leading to the contact d^{15} on the switch F . In the illustrations the terminals d^{15} and d^{16} of the instrument set D are purposely located in front of the terminals f^{15} and f^{16} with reference to the 75 direction of rotation of the wipers of the finder switch, in order to facilitate the description of the circuits which are successively established by the movement of the switch. 80

85

Automatic operation of the finder switch.

When the subscriber at station A removes his receiver and closes the hook contacts A^8 the following circuit is established: instrument A , wires A^2 a^3 , armature a^6 , contact a^2 , wire a' , relay A^5 , battery Z^2 , by ground to Z' , contact a^5 , armature a^4 , wires a^7 and A' back to A . The energizing of the actuating relay attracts the armature a^5 , completing the following circuit: ground z^4 armature a^5 contact f^6 , wire f^5 , spring f^{41} , contact f^{43} , wire f , contact f^4 , armature f^3 wire f^2 motor magnet 27^F , battery Z^4 to ground. 90

95

The foregoing is termed the starting circuit and that part extending from the contact f^{43} is common to every instrument circuit leading to the finder switch and coöperates with the several branches connected to the spring f^{41} any one of which may be closed 100 by its respective actuating relay, to primarily actuate the motor magnet, when the switching mechanism is in its normal position. The several circuit branches also serve to energize the relay F^6 simultaneously with the first 110 impulse of current transmitted to the motor magnet over the following circuit: ground z^4 armature a^5 , contact f^6 , wire f^5 , spring f^{41} , contact f^{43} wire f , relay F^6 , wire f' , relay F^3 , and battery Z^3 to ground. The 115 motor magnet and the relay F^6 in the two divisions of the aforescribed circuits being in parallel, are simultaneously energized; the motor magnet 27^F receiving an impulse of current causes the movable member of the 120 switch to be advanced one step, permitting the spring switch f^{41} to disengage the contact f^{43} and the four wipers to engage the first tier of contacts of an incoming line, for instance those of the line D , but as the 125 relay F^6 was also energized, the armatures f^6 and f^{13} thereon were attracted, the latter completing the following circuit: battery Z^4 , magnet 27^F , wire f^2 , armature f^3 , contact f^4 , wires f , f^{20} contact f^{19} , armature f^{13} . 130

120

125

130

wire f^{12} brush f^{18} contact d^{16} , wire D^{15} , contact d^{150} armature d^5 , to ground z^{14} .

It should be stated at this point that the core of the relay F^5 is provided with a copper jacket, or otherwise constructed, to render its operation sluggish, so that the armatures f^9 and f^{18} are not released the moment the armature f^8 is attracted by the motor magnet 27^F . For this reason it will be seen that the difference in the time constants of this magnet and its associate relay permits the armature f^8 of the former to continue its vibrations until the relay F^5 is deenergized.

15 The second and successive steps imparted to the movable elements of the finder switch are caused by successively completing the operating circuit of the motor magnet and the holding circuit of the slow relay F^5 , as 20 the switch brushes traverse the bank of contacts, and step from one set of terminals to another. As both of these circuits are completed through the brush or wiper f^{18} they are common to all of the instrument 25 circuits connected to the finder switch and the local wires such as A^{15} , D^{15} , constitute branches of said circuits which are controlled by the actuating relays of the respective instrument circuits. All of the 30 operating circuit branches are normally closed or connected to one side of the battery when the actuating relays are deenergized; while the starting circuit branches are all opened. Consequently the energizing 35 of a line relay reverses the condition of the branches, under its control, namely, it closes the starting circuit and opens the operating circuit. It will therefore be seen that each time the wiper f^{18} passes onto a 40 contact, grounded as at z^{14} , an additional impulse of current is given to the motor magnet of the switch and the onward movement of its wipers will continue until the wiper f^{18} reaches a terminal of the operating 45 holding circuit branch belonging to the incoming line on which the call was originated as said circuit branch will then be open at the actuating relay armature. This is shown in Fig. 6 in which the armature a^5 50 is held out of engagement with the contact a^{15} by the actuating relay A^5 which was energized when the circuit of instrument A, the calling line, was closed.

The cessation in the flow of current in 55 the circuits in the motor magnet, 27^F and the relay F^5 permits the armatures on the latter to restore or drop back to their normal position thus permanently breaking the operating circuit at the contact f^{19} . At 60 this time the brush or contact element f^{17} is in engagement with the terminal f^{15} and the following circuit is established:

Battery Z' , cut off relay A^6 , wire A^{16} , contact f^{15} brush f^{17} , wire f^8 , armature f^9 , con-

tact f^{10} , wire f^{11} ground z' , which energizes the cut-off relay A^6 , causing the armatures a^4 and a^6 to be pulled up, to take both sides of the battery Z^2 off of the telephone instrument circuit and deenergize the actuating relay A^5 . As the wipers F^2 — F^2 are at this time in engagement with the contacts A^{20} , A^{10} , respectively, the telephone circuit is then extended onward to the connector switch.

Restoring the finder switch to normal.

The restoring of the finder switch F occurs when the instrument circuit which is closed in the first instance to actuate it, is subsequently opened, as occurs when the calling subscriber hangs up his receiver and opens the hook contacts A^3 . The releasing magnet 36^F is arranged in a circuit which includes the corresponding magnet of the connector switch C , which may be traced on Figs. 6 and 7 of the drawings. In order to simplify the description at this point, a temporary circuit has been indicated in Fig. 6 by the dot and dash line, although the full release operation cannot be stated except in connection with the connector switch C , as there are contacts in the true circuit of the release magnet 36^F which are opened when the telephone instrument circuit is extended by the finder switch. The battery supplying current to the release magnet 36^F is indicated by Z^3 , and between it and said magnet is a current interrupter F^6 , which in the present illustration is shown as a rotary element adapted to be driven continuously by any suitable source of power, but as its function is merely to intermittently transmit current between its brushes f^{21} and f^{22} , it will be understood that a relay or some other similar device might be employed with equal facility for opening and closing this circuit. The brush f^{21} is connected directly to the battery, z^5 , and the brush f^{22} is joined by the wire f^{23} to one end of the coil of the magnet 36^F , the other end of said coil being connected by a circuit wire, f^{24} , as shown by the dot and dash lines, joined to the armature f^{25} , arranged on the controlling relay F^5 , which attracts the armature away from its back contact, f^{26} , connected by a wire f^{27} with the spring switch arm f^{41} . As before mentioned, the contact f^{42} is connected to the ground z^5 , which forms the other terminal of the battery Z^3 . It will be remembered that, during the rotation of the movable elements of the switch F , the controlling relay F^5 is energized, consequently the circuit of the release magnet is broken by the armature f^{25} despite the fact that the other opening in said circuit is closed by the spring switch arm f^{41} , upon the first movement of the switching mechanism. The circuit of

the release magnet 36^F, may be traced as follows; when the switching mechanism ceases operation: battery Z³, brush f²¹ current interrupter F⁶, brush f²², wire f²³, magnet 36^F wire f²⁴, armature f²⁵ contact f²⁶, wire f²⁷, spring switch f⁴¹, contact f⁴², to ground z⁵. The energizing of the release magnet causes the movement of its armature and the retraction of the detent and 10 pawl (parts 30 and 21, shown in Fig. 3), permitting the movable element to be returned to its normal position by the coil spring 20 (shown in Figs. 4 and 5.) The last described circuit is opened at the connector switch C before the slow operating relay F⁵ releases its several armatures, as will be more fully described hereinafter, so that the temporary circuit wire f²⁴ may be disregarded.

20 *The connector switch.*

The connector switch comprises apparatus common to all of the incoming lines, which is rendered operative as soon as the 25 finder switch has selected the particular line on which a call has been originated. The movement of this switch is controlled by mechanism which is actuated by impulses of current despatched in any suitable manner 30 but preferably by the impulse transmitter such as indicated by A⁴, located at the subscriber's station. This mechanism has for its primary object to control the operation of the movable contact elements or wipers 35 C'—C² to permit their adjustment into engagement with the terminal contacts of any instrument circuit on said switch and further, to render the circuit so connected (the outgoing called line) engaged or "busy" to 40 prevent the called subscriber from attempting to set up a different connection through the switches F and C, at this time. This mechanism is illustrated in detail in Fig. 7, and it is also shown upon a larger scale in 45 Fig. 8.

Associated with the connector switch is the signaling and answering mechanism, the operation of which is effected by virtue of the aforementioned controlling devices, 50 but as the circuits which are established for performing the functions of signaling and answering are not completed until after the controlling devices have performed their operations, this mechanism is illus- 55 trated separately in Fig. 10.

Among those persons versed in this art it is customary to designate the two conductors of a telephone circuit, (such as A', A²), as the line and mate wires, and as 60 these expressions will serve to elucidate further description, this nomenclature will be adopted.

In tracing the circuit from the switch F to the switch C, it will be seen that the line

and mate wires 4^A and 5^A, leading from the brushes, F'—F², (in Fig. 6) are extended as indicated by 4^A—5^A, (in Fig. 7) to the wipers C'—C² of the switch C, and have interposed therein condensers 47 and 48 and are supplied with current from the 70 battery Z by wires 49 and 50 leading to the line and mate respectively. Interposed in the battery wires 49 and 50 are line balancing coils 4^B—5^B, the latter being also used as a relay for performing one of the steps 75 in establishing the signaling circuit. The line and mate conductors, 4^A, 5^A, form the tie between the finder and connector switches and leading from these conductors are branches 40^A and 50^A, which are connected, respectively, to one end of the coil of the line relay 41^A and the coil of the mate relay 51^A. The other end of the coil of the first mentioned relay is connected by the 80 wire 4^a to a battery Z⁶ and the correspond- 85 ing extremity of the other coil is connected by a wire 5^a to a ground z⁶, corresponding to said battery, whereby a current impulse therefrom will cause both the line and mate relays to be energized when the brushes 90 F'—F² of the finder switch F are in coöperative engagement with the terminals of the incoming line. These two relays are associated with the motor magnet 27^C and the release magnet 36^C, of the C switch, and 95 together they control these magnets in the performance of their respective functions. These relays also have a time relationship, the mate relay being preferably the one which is so constructed as to have a more 100 sluggish or retarded action than the line relay, so that its armatures will be held in attracted position during the vibration of the armatures on the line relay. This is also true of the third or local relay C³ controlling armatures which close a circuit for 105 energizing the cut-off relay of the called or selected line to make the latter engaged or "busy." This relative timing of the mate relay 51^A and the local relay C³ permits 110 the motor magnet 27^C to be operated successively in unison with a group of impulses transmitted over the operating circuit by the impulse transmitter A⁴ at the subscriber's station, and to destroy said circuit 115 to prevent the operation of the motor magnet, and render it inoperative to other current impulses subsequently transmitted over said circuit. The line relay 41^A controls an armature c connected to one end of the coil 120 of the motor magnet 27^C by the wire c' and coöperating with a back contact, c² connected by the wire c³ with an armature c⁴, on the mate relay 51^A, which attracts it into engagement with a forward contact c⁵ connected to the battery Z⁷ by the wire c⁶. The 125 other end of the motor magnet coil is attached to the wire c⁷ which has a ground

z^7 over which current impulses from the battery Z^7 are received. It will be seen therefore that current in the line and mate wires simultaneously energizes the two relays, the line relay opening the circuit of the motor magnet by attracting the armature c at the instant the mate relay attracts the armature c^4 preventing the energizing of the motor magnet until the armature c is released.

The complete circuit of the line and mate relays can be traced as follows: Fig. 7, battery Z^6 , wire 4^a line relay 41^A , wires 40^A 4^A , Fig. 6, wire 4, brush F' contact A^{20} , wire A^2 , instrument A, wire A' , contact A^{10} , brush F², wires 5 , 5^A , (Fig. 7) 50^A , mate relay 51^A , wire 5^a , to ground z^6 . The operator at subscriber's station A now despatches the desired number of impulses over the aforesaid circuit, to actuate the connector switch, and cause its wipers, C'—C², to move into engagement with the terminal contacts of the outgoing line circuit, on which he desires to call a certain party, by opening and closing the circuit delineated above, the requisite number of times with sufficient rapidity to release the armature c and to continue its vibration to successively close and open the circuit of the motor magnet 27^c .

To illustrate this selective operation succinctly, let it be considered that the called subscriber's station, heretofore referred to as B, is the instrument of which the line and mate wires are connected with the set of contacts designated by the numeral 400 in Fig. 3, which is the fortieth set of contacts in the bank of contacts of the connector switch, necessitating forty steps of the movable contact elements or brushes before the latter can engage them. The impulse transmitter, A^4 will, therefore, be operated to open and close the contacts A^{41} and A^{42} , forty times; each impulse of current over the incoming line and mate wires (A' A^2 , 4^A — 5^A) will energize both the line and mate relays, 41^A — 51^A , but as the latter has a slow or retarded action, it does not release the armature c^4 , and the latter is, therefore, held in engagement with the contact c^5 during the vibration of the armature c which is attracted and released each time the incoming circuit is closed and opened. Consequently a series of impulses in unison with those transmitted over the incoming circuit by the successive opening and closing of the contacts A^{41} and A^{42} , at station A, are transmitted over the motor magnet circuit, which may be traced as follows: battery Z^7 , wire c^6 , contact c^5 , armature c^4 , wire c^3 , contact c^2 , armature c , wire c' , magnet 27^c , wire c' , to ground Z^7 . Upon the cessation of these impulses the brushes of the connector switch stand in the position shown in dotted lines in Fig. 3. In considering Fig. 7 further, the brushes C'—C² will be

borne in mind as engaging the contacts B^{21} and B^{11} .

Rendering a called line engaged or busy.

Each set of terminals on the connector switch comprises a third terminal corresponding with and bonded to the terminal on the finder switch devoted to the circuit of the cut-off relay associated with each instrument circuit. This third terminal of the circuit of instrument B, is indicated by c^{15} which is shown as connected to the cut-off relay B^6 by the wire B^{16} . Coöperating with this contact is the wiper c^{17} , from which leads the wire c^8 , terminating in an armature c^9 arranged on the local relay C^3 , and coöperating with a back contact, c^{10} , connected to a ground z^8 , over which current impulses are received from the battery Z^8 , connected with the coil of the cut-off relay B^6 , and supplying current to the following circuit: battery Z^8 , relay B^6 , wire B^{16} , contact c^{15} , brush c^{17} , wire c^8 , armature c^9 , contact c^{10} , to ground, z^8 . The foregoing circuit energizes the cut-off relay of the outgoing called line to prevent the called subscriber from disturbing the finder switch when he answers the call and closes his line through the hook contacts B^3 . The complete talking circuit from instrument A, the calling line, to instrument B, the called line, may now be traced as follows: Fig. 7, condenser 47, wire 4^A , (Fig. 6) wire 4, brush F', contact A^{20} , wire A^2 , instrument A; wire A' , contact A^{10} , brush F², wire 5, (Fig. 7) wire 5^A , condenser 48, brush C², contact B^{11} , wire B' , instrument B; wire B^2 , contact B^{21} , brush C', wire 4^A . Current is supplied for part of the talking circuit from the battery Z to the two conductors 4^A and 5^A by the wires 49 and 50 and the other part of the circuit is supplied with current from battery Z^8 .

Delineated on Fig. 7 are the bond wires connecting the corresponding terminals of the lines of instruments A, B, and D, on the switches F and C, which arrangement allows a call to be initiated on any line and permits one to be received from any other line. These bonds leading to switch C, are designated as follows: A^{100} , leading from the wire A' to the contact A^{101} ; A^{200} leading from the wire A^2 to the contact A^{201} ; and the wire A^{160} , leading from the wire A^{16} , to the contact A^{161} .

In order to prevent the operation of the cut-off relays of those lines of the connector switch whose terminals are traversed by the brush c^{17} , the circuit of said brush is opened during the rotary movement of the connector switch and it is to this end that the armature c^9 is arranged on the local relay C^3 . One end of the coil of this relay is connected by the wire c^{11} , with the back contact c^{13} , with which the spring switch c^{11}

is held in engagement by the pin c^{45} , on the movable member of the switch C, when the latter is in its normal position. The other end of said coil is extended by the 5 wire c^{12} to an armature c^{13} , on the mate relay 51^A , which coöperates with a forward contact c^{14} , connected by the wire c^{150} , to the wire c^6 , leading to the battery Z^7 . The spring c^{41} is connected by the wire c^{18} to a 10 ground, Z^{17} receiving impulses of current from the battery Z^7 , from which it follows that, when the mate relay, 51^A is energized, the following circuit is established: battery Z^7 , wires c^6 , and c^{150} , contact c^{14} , armature c^{13} , wire c^{12} , relay C^3 , wire c^{11} , contact c^{48} , 15 spring switch c^{41} , wire c^{16} , to ground z^{17} , thus energizing the local relay C^3 , and opening the circuit of the brush c^{17} , at the armature c^9 . A holding circuit is established for 20 retaining current in the local relay C^3 , during the operation of the motor magnet 27^C , by connecting to the wire c^{11} an armature c^{18} , which is attracted into engagement with the terminal c^{19} , of the wire c^{20} , which terminates in a back contact c^{21} of an armature c^{22} , (on the line relay 41^A) connected by a wire c^{23} , with a ground z^{70} , also adapted to receive current impulses from the battery Z^7 . This holding circuit may be traced 25 as follows: battery Z^7 , wires c^6 , c^{150} , contact c^{14} , armature c^{13} , wire c^{12} , relay C^3 , wire c^{11} , armature c^{18} , contact c^{19} , wire c^{20} , contact c^{21} , armature c^{22} , wire c^{23} , to ground z^{70} . Now, as both the relays C^3 and 51^A are so 30 constructed as to discharge their residual magnetism slower than the line relay 41^A does, the armatures c^{18} and c^{13} are held in attracted position during the vibration of the armature c^{22} and each movement of 35 40 which supplies the current necessary to keep up the magnetism in the relay C^3 until the pulsations of current over the line and mate conductors cease.

Upon the cessation of impulses from the 45 impulse transmitter, A^4 , the contacts A^{41} , A^{42} thereof, are in engagement thus, leaving the telephone circuit closed and causing a break in the regularity of the transmission of said impulses, so that the line relay is 50 energized holding the armatures c and c^{22} in attracted position. This interruption arrests the motor magnet 27^C and allows the magnetism in the core of the relay C^3 to seep or leak out, to close the circuit of the 55 cut-off relay B^6 , of the selected outgoing line.

Restoring the connector switch to normal.

In order to prevent the return of the connector switch to its normal position and to thwart a similar movement of the finder switch, the release magnets, 36^F and 36^G are arranged in a compound circuit, which is 60 opened when the line and mate conductors of an incoming or calling line, are energized.

This is accomplished by extending the circuit of each of said magnets through an armature 136 which is attracted when the mate relay 51^A is energized. This armature normally rests against the back contact c^{24} , 70 connected by a wire c^{25} with one end of the coil of the release magnet 36^G and similarly connected by a wire c^{26} with one end of the coil of the release magnet 36^F of the switch F. The other terminal of the coil 36^G is connected by a wire c^{27} , with a brush c^{28} , of a current interrupter, C^6 , with which coöperates the brush c^{29} , leading to the battery Z^{50} . The current interrupting devices of the switches F and C, are, in practice, one and 80 the same, and the batteries Z^{50} , and Z^5 , represent the source of current supply from a main battery—all as shown in Fig. 8. The armature 136 is connected by the wire c^{30} , with the forward contact c^{42} , of the pair of 85 contacts coöperating with the spring switch arm c^{41} . This armature is also connected by the wire c^{31} to the armature f^{25} , shown in Fig. 6, on the relay F⁵. When the connector switch has been actuated out of its normal 90 position, the spring switch arm c^{41} engages the back contact, c^{42} , and when the circuit over the line and mate conductors is broken, by the opening of the contacts at the subscriber's station, such as A^3 , the armature 95 136 is released and engages the back contact c^{24} , completing the following circuit: (switch C Fig. 7) battery Z^{50} , brush c^{29} , current interrupter C^6 , brush c^{28} , wire c^{27} , release relay 36^G , wire c^{25} , contact c^{24} , armature 136 , 100 wire c^{30} , contact c^{42} , spring switch c^{41} , wire c^{16} , to ground z^{17} , over which the impulse or impulses, of current are sent to permit the movable element of the switch C to return to its normal position. At this same instant 105 the following circuit has also been completed: (switch F, Fig. 6) battery Z^5 , brush f^{21} , current interrupter F^6 , brush f^{22} , wire f^{23} , magnet 36^F , wire c^{28} , (Fig. 7,) contact c^{24} , armature 136 , wires c^{30} , c^{31} , (Fig. 6,) armature f^{25} , 110 contact f^{26} , wire f^{27} , spring arm f^{41} , contact f^{42} , to ground, z^6 . When the two switches, F. and C, are idle the armatures f^{25} and 136 are each in engagement with their back contacts so that if the movable elements of 115 either, or both, of the switches F and C are adjusted out of their normal position by manual manipulation, they will be returned by current operating the separate releasing magnets over the aforescribed circuits. It 120 will also be seen that if for any reason the finder switch F fails to pick up the line on which a call was originated, the movable element will make a complete excursion over all of the terminals in its bank of contacts, passing off the last set of terminals, when it is released and allowed to return to its normal position to successively repeat this operation until the incoming line has been picked up. It will be understood that this repeating 125 130

movement results only when an unnatural condition exists, such as a delay occurring in the operation of one or another of the relays, particularly the cut-off relay of the calling line, which might occur if the third brush, f^{17} of the finder switch, should fail to establish a circuit with the respective contact f^{15} , the first time it is stepped into engagement therewith. Likewise, if for any reason a subscriber should open the line by hanging up his receiver immediately after it had been removed from the hook, the finder switch would automatically return to its normal position in readiness to be again started upon an impulse of current received over the starting circuit branch of any of the incoming lines.

Opening the line.

20 In exchanges serving a large number of telephone instrument circuits, the finder and connector switches are duplicated as many times as need be, and on each switch appear the terminals of the line and mate conductors, which may be extended as shown in dotted lines in Fig. 7, provisions not referred to herein, being made whereby, two or more connections may be set up at the same time. With such an arrangement of 25 switches, it will be seen that where two line circuits are connected over one set of switches, the movable contact elements of another set of switches in traversing their respective banks of contacts to effect a second connection may pass over the unoccupied terminals of the instrument circuits 30 previously established. Therefore, if said wipers are supplied with current during their forward and retrograde movements a disagreeable click will be heard in the receiver of said connected telephone instruments. It has been previously intimated that in order to remove these objectionable noises provision is made for opening the line 35 and mate conductors between the finder and connector switches during the time the finder switch is advancing to pick up an incoming line and also for the moment of time when both switches are released, and 40 are returning to normal position. This is accomplished in the present instance by means of the two relays F^3 , and F^4 , each controlling a pair of armatures, one of each of said pair being located in the circuit of the line and mate conductors respectively. The 45 relay F^3 , has been described as being in the circuit of the wire f' by means of which it receives current from the battery Z^3 and is energized during the operation of the motor magnet 27^F . The relay F^4 is another one of the so-called slow or retarded relays, one terminal of its coil being connected by the wire f^{28} to the wire f^{23} , the other end of the coil being connected by the wire f^{29} , to the 50 wire c^{26} , whereby said relay is energized

simultaneously with the release magnet 36^F , whenever the circuit of the latter is closed by current impulses transmitted from the current interrupter, F^6 . The armatures in the line conductor 4 are indicated by 42^a and 43^a , the former being connected to the wire 4 and coöperating with the back contact, 44^a , joined by the wire 45^a to the armature 43^a , which normally engages the back contact 46^a , forming the terminal of the wire 4^A . The armatures of the mate conductor 5 are indicated by 52^a and 53^a , which are connected by a wire 54^a , the former armature engaging a back contact or terminal 55^a of the wire 5, and the latter coöperating with the back contact or terminal 56^a , of the wire 5^A . When the two relays F^3 and F^4 are de-energized their armatures are in the normal position (shown in Fig. 6) and this part of the "talking circuit" is traceable as follows: line conductor 4, armature 42^a , contact 44^a , wire 45^a , armature 43^a , contact 46^a , wire 4^A ; mate conductor 5, contact 55^a , armature 52^a , wire 54^a , armature 53^a , contact 56^a , wire 5^A .

Ringing and answering circuit.

The description thus far has been confined to the operation of the various elements which occur in the setting up of the connections between two telephone lines and to the mechanism operating conjointly therewith by means of which a connection is automatically broken and the switches restored to their normal position. There still remains for further consideration additional mechanism by means of which the signaling devices on the outgoing or called lines are operated, after the connection has been established, which are illustrated particularly in Fig. 9.

Each telephone instrument is provided with signaling devices, such as the usual ringer, (indicated by B^7 , at station B, Fig. 9) which are energized by signaling current from the generator C^7 , supplied to the outgoing line circuit, such as the wires B' — B^2 . In order to supply this current intermittently to ring the bells, or operate the signaling devices periodically, as well as to afford the answering subscriber an opportunity to cut his instrument into the line, a signaling relay C^8 , is employed. This relay is rendered operative by the conjoint operation of the line relay 41^a and the local relay C^3 , the latter acting to temporarily render the signaling relay inoperative and open the conductors between the source of signaling current and the movable contact elements, during the rotation of the brushes of the connector switch, so that the signaling devices of other circuits are not operated as the brushes of this switch traverse their terminals in seeking those of the selected line.

One end of the coil of the signaling relay C^8 is connected by the wire c^{32} to an arma-

- ture c^{38} , which is attracted, when the balancing coil 5^B , is energized, into engagement with the forward contact c^{34} , of the wire c^{35} , leading to the battery Z^9 . The 5 armature c^{33} when in normal position cooperates with a back contact c^{36} , connected, by a wire c^{37} , to a brush c^{38} of the current interrupter C^9 , the second brush c^{39} , of which is connected with the battery Z^{10} .
- 10 The other extremity of the coil of the relay C^8 is connected by a wire c^{40} to an armature c^{410} , which is held in attracted position with a forward contact c^{420} , when the line relay 41^A is energized. The contact c^{420} is joined 75 by the wire c^{430} to a back contact c^{44} , of an armature c^{45} on the local relay C^3 , said armature being connected to a ground z^{100} , which completes the circuit from the grounded sides of the batteries Z^9 and Z^{10} .
- 15 Instead of extending the line and mate conductors 4^A and 5^A directly to the brushes C' and C^2 (as shown in Fig. 7) they are terminated in contacts 47^a and 57^a with which coöperate armatures 48^a and 58^a , on 80 20 the signaling relay C^8 , said armatures being connected respectively with brushes C' and C^2 by wires 49^a and 59^a . The brushes c^{47} and c^{48} of the current generator C^7 are connected respectively by wires c^{49} and c^{50} .
- 25 30 to a back contact c^{51} , of the armature 58^a , and an armature c^{52} , on the mate relay 51^A . The armature c^{52} , when in attracted position, engages a contact c^{53} , connected, by a wire c^{54} , to a back contact c^{55} , of the armature 48^a . It will be remembered that the line and mate relays 41^A and 51^A , are energized during all of the operations occurring on the connector switch, consequently when a line circuit is extended to the latter, from 35 40 the finder switch, the armatures c^{410} and c^{52} are attracted and held in engagement with their respective contacts and that when said switch picks up the outgoing called line the local relay C^3 is deenergized, permitting 45 50 the armature c^{45} to drop into engagement with its back contact, c^{44} . The following circuit is then established: battery Z^{10} , brush c^{39} , current interrupter C^9 , brush c^{38} , wire c^{37} , contact c^{36} , armature c^{33} , wire c^{32} , signaling relay C^8 , wire c^{40} ; armature c^{410} , contact c^{420} , wire c^{430} , contact c^{44} , armature c^{45} , to ground, z^{100} .
- The last mentioned current interrupter C^9 , is in practice, the same as C^6 and F^6 , and 55 it serves to intermittently energize the signaling relay, which then attracts the armatures 48^a and 58^a , in the line and mate conductors, in momentary engagement with the contacts 47^a and 57^a . Now if it should happen 60 65 that during the moment of time in which these armatures are attracted the subscriber should close his line at the receiver hook contacts B^3 , the following circuit will be established from instrument B to battery Z : battery Z , coil 4^B , wires 49 , 4^A , contact 47^a , armature 48^a , wire 49^a , armature 60^a , contact 61^a , wire 49^a , brush C' , contact B^{21} , wire B^2 , contacts B^3 , instrument B , wire B' , contact B^{11} , brush C^2 , wire 59^a , (contact 71^a , armature 70^a), armature 58^a , 70 contact 57^a , wires 5^A , 50 , coil 5^B , battery Z . This circuit energizes the coil 5^B and attracts the armature c^{33} , which cuts out the current interrupter C^9 , and in place thereof substitutes continuous current from the battery Z^9 , causing said current to be retained in the signaling relay C^8 , which latter holds the aforescribed line circuit closed until one or both of the subscribers open the connected circuit between their two instruments. 75 80
- In order to prevent the signaling current from being despatched over the outgoing instrument circuits successively, as the movable contact elements are advanced progressively, the parts 49^a and 59^a of the line and mate conductors are each provided with an opening adapted to be normally closed by armatures 60^a — 70^a , coöperating with contacts 61^a — 71^a . These armatures are arranged on the local relay C^3 , and are attracted by it during the time the connector switch mechanism is selecting the given line circuit. 85 90 95
- The armatures 48^a and 58^a normally stand in engagement with their back contacts and therefore the instant the wipers C' — C^2 pick up the selected line and the local relay C^3 releases the armatures 60^a — 70^a , the ringing current is despatched from the generator C^7 , 100 to operate the signaling devices B^7 , over the following circuit, (shown in Fig. 9): current generator C^7 , brush c^{48} , wire c^{50} , armature c^{52} , contact c^{53} , wire c^{54} , contact c^{55} , armatures 48^a , 60^a , contact 61^a , wire 49^a , 105 brush C' , contact B^{21} , wire B^2 , ringer B^7 , wire B' , contact B^{11} , brush C^2 , wire 59^a , contact 71^a , armatures 70^a , 58^a , contact c^{51} , wire c^{49} , brush c^{47} , generator C^7 . 110
- Multiple switches.*
- The length of time required to set up a connection, or establish a call, may be greatly shortened or minimized by employing a multiple arrangement of finder switches, preferably arranged in pairs, the equivalent sets of terminals on each being arranged relatively in reverse position in the banks of contacts on the two switches, which in practice gives the same result as 115 would be obtained if the mechanism of one switch of a pair was designed to drive its contact elements in a reverse direction relatively to the movement of the wipers of the other switch. The switch illustrated in Fig. 3 is provided with fifty sets of line circuit terminals, requiring fifty movements or steps of the wipers to bring them into engagement with the last set of terminals, and, although the switch mechanism travels with 120 125 130

considerable alacrity, it will be seen that the time required to enable the switch wipers to move into engagement with the last set of terminals, is twice as long as that consumed 5 while the wipers are moving to the center of the bank of contacts to engage the twenty-fifth set of terminals. Consequently by tying each line circuit to two switches and either arranging the terminals thereon 10 in inverse order or rotating the wipers of one of them in a relatively opposite direction to those of the other switch the total number of lines may be traversed in twenty-five steps thereby reducing the time to one-half of that required by a single switch for 15 making the selection of a line having the highest number.

To describe this idea more specifically: The circuit of instrument B was stated to 20 be connected to the fortieth set of contacts, designated by 400 in Fig. 3, requiring forty steps of the finder switch F. On a second finder switch (such as F¹⁰, Fig. 10), the circuit of instrument B would be joined to the 25 tenth set of terminals, occupying the position designated by 100 in Fig. 3, so that the movable contact elements of this second switch would only be required to move ten steps to select said instrument circuit. In 30 Fig. 10 this duplication of finder switches is illustrated diagrammatically to show the arrangement of terminals corresponding to the circuits of instruments A and D, of Figs. 6 and 7. The switches F and C are identical 35 with those shown in said figures, and the operating mechanism of the other finder switch F¹⁰, is like that of the switch F, but associated with it is a separate connector switch C¹⁰, which performs the same function 40 as the corresponding switch C, when an instrument circuit is selected by the finder switch F¹⁰. It will be noticed that the sets of terminal contacts A¹⁷—D¹⁷ on the latter, are in reverse position in the 45 switch bank, relatively to the corresponding sets A⁷—D⁷ on the switch F, while the sets of connector switch terminals D⁸—D¹⁸ and A⁸—A¹⁸ occupy the same relative position in the two switch banks. 50 The finder switch F¹⁰ is adapted to be actuated simultaneously with the switch F and to this end its spring contact arm f¹⁴¹ is also connected to all of the starting circuit branches by the wire f⁵⁰, which causes 55 both switches to start out to find a calling line circuit. The switch, the movable elements of which first pick up the terminals of said calling line circuit, will be arrested, as heretofore described, while the other 60 finder switch continues its excursion. It will be recollected that the instant the finder switch is arrested the cut-off relay of the calling line is energized, permitting the operating-holding circuit branch, (previously 65 opened) to be closed. The closing of this

circuit branch occurs before the movable contact elements or wipers of the other finder switch (which is still advancing) engage the second set of terminals of the connected calling circuit. Consequently this 70 finder switch is not arrested at said set of terminals but is permitted to pass over the entire bank of contacts until disengaging the last set of terminals when it is automatically returned to its normal position. If the 75 finder switch F¹⁰ happens to be the one which picks up the incoming calling circuit then the latter is extended to the associate connector switch C¹⁰, which is operated to select the desired outgoing called circuit, 80 the other connector switch C remaining idle.

In addition to facilitating the quick selection of an incoming calling circuit, as before mentioned, this duplication of the 85 finder switches possesses the advantage of making the selection of a circuit doubly assured, for should the movable contact elements of one switch happen to miss a connection, due to corroded terminals, or a too 90 rapid movement of the wipers, or some other unaccountable cause, then the other finder switch will pick it up.

Sub-station lamps.

To assist a subscriber in the manipulation of his impulse transmitter and the selection of other subscribers' numbers, from his directory, as well as to inform him of the operativeness of his own instrument circuit, 100 an incandescent lamp, such as A⁹—B⁹—D⁹, is located at a suitable point in proximity to each instrument set. This lamp is arranged in the circuit of either the line or mate conductors which receive current whenever the 105 instrument circuit is closed. The location of the lamp in the instrument circuit is rendered possible by virtue of the arrangement of the switching mechanism which is controlled entirely by impulses of current transmitted over the two instrument circuit conductors and is not dependent for its operation upon earth connections, or a third line 110 wire, coöperating with one or both of the usual line and mate conductors.

I claim as my invention:

1. In a telephone system, the combination with a switching mechanism comprising a plurality of terminals arranged in sets, separate contact elements coöperating with 120 each of said sets, a motor magnet for operating them and a plurality of instrument circuits, of a motor magnet relay, a starting circuit for said magnet and relay and an operating circuit controlled by the relay, said 125 circuit leading through one of the elements and comprising branches leading from one set of switch terminals and corresponding to each of the several instrument circuits, an actuating relay controlling each of said 130

- branches, a circuit therefor which is energized when its respective instrument circuit is closed, a cut-off relay controlling each actuating circuit, a separate circuit for each 5 cut-off relay including a conductor leading to one of the other set of terminals and a conductor leading to the element coöperating therewith, contacts in said conductor which are opened by the motor magnet relay, means for causing the flow of current in the operating circuit to pulsate and a source of current supply for said circuits.
2. In a telephone system, the combination with a switching mechanism comprising a 15 plurality of terminals, a contact element coöperating therewith, a motor magnet for operating it progressively and a plurality of instrument circuits, of a motor magnet relay, a starting circuit for energizing said 20 magnet and relay and an operating circuit controlled by the relay, said circuit leading through the element and comprising branches leading to the switch terminals and corresponding to the several instrument 25 circuits, means for rendering the branches operative when their respective instrument circuits are rendered inoperative, means for causing the flow of current in the operating circuit to pulsate and a source of current 30 supply for said circuits.
3. In a telephone system, the combination with a plurality of instrument circuits, a switching mechanism comprising a plurality of terminals corresponding to the instrument 35 circuits, a movable contact element coöperating therewith, and a motor magnet, a motor magnet relay and a starting circuit for energizing the magnet and relay, of an operating circuit closed by the relay which 40 includes the contact element and circuit branches leading from the switch terminals, means for rendering the operating circuit inoperative when the element engages the terminal of a branch whose corresponding 45 instrument circuit has been rendered operative, means for causing the flow of current in the operating circuit to pulsate and a source of current supply for said circuits.
4. In a telephone system, the combination with a plurality of instrument circuits, a switching mechanism comprising a plurality of terminals corresponding to the instrument circuits, a movable contact element coöperating therewith and a motor 55 magnet, a relay associated therewith which is arranged to respond to impulses of current with less rapidity than the motor magnet, a starting circuit for energizing the magnet and relay, of an operating circuit 60 closed by the relay which includes the contact element and branches leading from the switch terminals, a relay associated with each instrument circuit adapted to be operated, when its instrument circuit is rendered operative, for opening the correspond-
- ing branch of the operating circuit to arrest the contact element when it engages the terminal of said branch, means for causing the flow of current in the operating circuit to pulsate and a source of current supply for 70 said circuits.
5. In a telephone system, the combination with a plurality of instrument circuits, a switching mechanism comprising a plurality of terminals arranged in sets corresponding 75 to the instrument circuits, separate contact elements coöperating with each of said sets of terminals and a motor magnet for operating the contact elements, of a relay associated therewith which is arranged to respond to impulses of current with less rapidity than the motor magnet, a starting circuit for energizing the magnet and relay, an operating circuit for said parts which is closed by the relay and includes one of the 80 contact elements and circuit branches leading from the coöperating set of terminals as the said terminals are successively engaged, a set of normally closed contacts in each of said circuit branches, an actuating relay associated with each instrument circuit for opening said contacts, a separate circuit for the actuating relay which is energized when the corresponding instrument circuit is rendered 85 operative, a cut-off relay controlling each 90 actuating relay circuit, a circuit for each cut-off relay comprising a conductor leading to one of the other set of terminals, the contact element coöperating therewith and a conductor leading from said element, contacts in said cut-off relay circuit which are opened during the operation of the motor magnet, means for causing the flow of current in the operating circuit to pulsate and a source of current supply for said circuits. 95
6. In a telephone exchange system, the combination with an incoming instrument circuit and an outgoing instrument circuit, of a finder switch having a terminal for the incoming circuit, a connector switch having 100 a terminal for the outgoing circuit, movable contact elements on each switch coöperating with their respective terminals and a conductor connecting said elements having normally closed contacts therein, 105 electromagnetic mechanism for operating the elements, means for opening the contacts in the conductor during the movement of said elements and a source of current supply for said circuits. 110
7. In a telephone exchange system, the combination with two instrument circuits, of two switching mechanisms, each comprising an immutable contact forming a terminal for one of the circuits, and a moving element coöperating therewith, said elements being normally in electrical connection and serving to connect one circuit with the other when in engagement with their respective terminals, mechanism for operating 115 120 125 130

- ing the elements, means for breaking said connection between the elements during the movement of the switching mechanism and a source of current supply for said circuits.
- 5 8. In a telephone exchange system, the combination with two instrument circuits, two switching mechanisms, each comprising an immutable contact forming terminals for said circuits and movable elements co-
10 operating therewith, of operating mechanism for actuating the movable elements of the switches, means operating conjointly with one of the said mechanisms to temporarily render the other mechanism in-
15 operative, normally closed connections between the elements of the switches completing the circuit between the separate instrument circuits when said elements are in engagement with their respective terminals,
20 and a source of current supply for said circuits.
9. In a telephone exchange system, the combination with two instrument circuits, two normally open switching mechanisms
25 each comprising a terminal for one of the circuits and movable contact elements co-
operating therewith, of a tie between the elements which completes the instrument circuits when the elements engage their re-
30 spective terminals, an electromagnetic mechanism actuated by impulses of current on one of the circuits for operating the movable contact element of one of the switches when one of the instrument circuits is closed, a
35 similar mechanism for operating the movable element of the other switch which is normally inoperative and is rendered operative upon the cessation of movement of the mechanism of the first mentioned switch,
40 means for subsequently operating said mechanism, and a source of current supply for said circuits.
10. In a telephone exchange system, the combination with two normally open instru-
45 ment circuits, a finder and a connector switch, both comprising terminals for each circuit, and movable contact elements co-
operating therewith and normally in elec-
50 trical connection to complete the instrument circuits when they engage their respective terminals, of electromagnetic mechanism which is actuated when one of the circuits is closed to move the element of the finder switch into engagement with the terminal of
55 said closed circuit, similar mechanism for operating the element of the connector switch which is normally inoperative and is rendered operative upon the completion of the movement of the parts of the finder
60 switch, means for subsequently operating said connector switch mechanism, and a source of current supply for said circuits.
11. In a telephone exchange system, the combination with two normally open cir-
65 cuits, a finder switch and a connector switch both comprising terminals for each circuit and electrically connected movable contact elements co-operating with the terminals to connect the instrument circuits, of electro-
70 magnetic mechanism for actuating the ele-
ment of the finder switch into engagement with the terminal of one of the circuits when said circuit is closed, similar mechanism for actuating the element of the connector switch into engagement with the terminal of
75 the other circuit, devices for restoring the switch elements to their normal position and means operating conjointly therewith for rendering the operating mechanism of the connector switch inoperative, and a
80 source of current supply for said circuits.
12. In a telephone exchange system, the combination with two instrument circuits, two switches each comprising an immutable contact forming a terminal for one of the circuits and a movable contact element co-
85 operating therewith, said elements being normally electrically connected and serving to connect one circuit with the other when in engagement with their respective terminals, of mechanisms for actuating the respective elements and devices for restoring them to their normal position, means operating conjointly with the restoring devices for breaking said connection between the
90 switch elements during the return movement of the latter and a source of current supply for said circuits.
13. In a telephone exchange system, the combination with two instrument circuits each comprising a line and a mate conductor, two switches each comprising a terminal for the line and mate conductors of each circuit and separate movable contact elements co-operating with the line and mate terminals, of two ties normally connecting the corresponding elements of the switches, mechanism for operating the switch elements, means operating conjointly with said mechanism for opening the ties during the
95 switching operation and a source of current supply for said circuits.
14. In a telephone exchange system, the combination with two instrument circuits each comprising a line and a mate conductor, two switches both comprising terminals for the line and mate conductors of each circuit, said terminals being arranged in sets, and separate movable contact elements co-operating with said sets of terminals, of two ties connecting the corresponding elements of the switches, mechanism for operating the switch elements in one direction to connect one instrument circuit with another and devices for restoring them to their normal position, means operating conjointly with the operating mechanism to
100 open the ties when the switch mechanism is
105
- 110
- 115
- 120
- 125

setting up a connection and similar means associated with the restoring devices for opening the ties when the connection is being destroyed and a source of current supply for said circuits.

15. In a telephone exchange system, the combination with two instrument circuits each comprising a line and a mate conductor, a finder switch and a connector switch each comprising terminals for the line and mate conductor of one of the circuits and separate movable contact elements coöperating respectively with the line and mate terminals of each switch, the corresponding 65 elements of said switches being in electrical connection and serving to connect the line and mate conductors of the instrument circuits through the switches when they are in engagement with their respective terminals, of mechanisms for operating the contact elements of the two switches, two relays controlling the connector switch mechanism each being arranged to respond to impulses of current on one of the instrument 70 circuits when the finder switch elements engage the terminals thereof, means for temporarily rendering said relays inoperative during the movement of the finder switch elements and a source of current supply for 75 said circuits.

16. In a telephone exchange system, the combination with a finder and a connector switch each comprising movable contact elements and separate sets of terminals coöperating therewith, a plurality of full metallic incoming instrument circuits comprising line and mate conductors each joined to one of the terminals of each set and a plurality of outgoing instrument circuits leading 80 from similar terminals of the connector switch, of electromagnetic mechanism common to all of the incoming instrument circuits and adapted to be actuated by impulses of current on any one of them to cause the 85 elements of the finder switch to move into engagement with the terminals of the said actuating circuit, conductors connecting the corresponding elements of the two switches, operating mechanism for moving the elements of the connector switch, electromagnetic devices controlling said operating mechanism which are responsive to current impulses in said conductors, means for causing current transmitted to the controlling 90 95 devices to pulsate and a source of current supply for said circuits.

17. In a telephone exchange system, the combination with a plurality of normally open incoming instrument circuits each comprising a line and a mate conductor, a finder switch comprising a plurality of terminals one for each conductor of each line, said terminals being arranged in sets and a movable contact element coöperating with each

set, of electromagnetic mechanism actuated 65 when one or another of said instrument circuits is closed to move the switch elements into engagement with the respective terminals of said instrument circuits, a connector switch comprising similar sets of terminals and movable elements coöperating therewith, outgoing instrument circuits leading from said terminals and electromagnetic mechanism actuated by successive impulses of current transmitted over the 70 incoming circuit, selected by the finder switch, for moving the connector switch elements successively into engagement with the 75 said outgoing circuit terminals, means for transmitting current impulses over the incoming circuit and a source of current supply for 80 said circuits.

18. In a telephone exchange system, the combination with incoming and outgoing instrument circuits which are normally 85 open, a finder and a connector switch each having terminals for each circuit and comprising movable contact elements coöperating with said terminals to connect the two 90 circuits, mechanism for operating the element of the finder switch, an actuating relay associated with each instrument circuit which is operated when its instrument circuit is closed to start said mechanism, a circuit for each actuating relay and a cut-off relay for 95 opening each actuating relay circuit, of a circuit for each cut-off relay, a set of terminals arranged on the connector switch devoted to the cut-off relay circuits and an additional element coöperating therewith 100 through which said circuits are completed, means for operating the elements of the connector switch to pick up the outgoing instrument circuit and complete the circuit of the cut-off relay associated therewith and a 105 source of current supply for said circuits.

19. In a telephone exchange system, the combination with a plurality of incoming and outgoing instrument circuits, a finder switch and a connector switch each having 110 terminals for each circuit and comprising movable contact elements coöperating with said terminals which are in electrical connection and serve to connect one instrument circuit with another, mechanism for operating the element of the finder switch, an actuating relay associated with each instrument circuit which is operated when its instrument circuit is closed to start said mechanism, a cut-off relay controlling each actuating relay, a circuit for each cut-off relay, and a set of terminals arranged on the connector switch devoted to the cut-off relay circuits, of an additional contact element 115 coöperating with said terminals through which said circuits are completed, mechanism for operating the elements of the connector switch to select a particular outgoing 120 125

instrument circuit, means operating conjointly with said mechanism for rendering the cut-off relay circuits inoperative during the movement of said switch elements and a 5 source of current supply for said circuits.

20. In a telephone exchange system, the combination with a plurality of normally open incoming and outgoing instrument circuits, a finder switch and a connector switch 10 each having terminals for each circuit and comprising movable contact elements coöperating with said terminals which are in electrical connection and serve to connect one instrument circuit with another, mechanism 15 for operating the element of the finder switch which is actuated when one of the instrument circuits is closed, a cut-off relay associated with each instrument circuit which when actuated prevents the 20 operation of the finder switch upon the closing of its associated instrument circuit, of a circuit for each cut-off relay, a set of terminals arranged on the connector switch devoted to the cut-off relay circuits and an 25 additional contact element coöperating with said terminals through which said cut-off relay circuits are completed, mechanism for operating the elements of the connector switch to select a particular outgoing instrument 30 circuit and a source of current supply for said circuits.

21. In a telephone exchange system, the combination with a plurality of normally open incoming and outgoing instrument circuits, each comprising a line and a mate 35 conductor, finder and connector switches both of which have terminals for both conductors of each line arranged in sets and also comprising movable contact elements 40 adapted to coöperate with said sets of terminals, conductors connecting the corresponding contact elements of the two switches and forming line and mate connectors, of mechanism for operating the elements 45 of the finder switch which is rendered operative when one of the instrument circuits is closed, a cut-off relay associated with each instrument circuit which when actuated prevents the operation of the finder 50 switch, a circuit for each cut-off relay, a set of terminals on the connector switch devoted to said circuits, an additional element coöperating therewith and a circuit branch leading therefrom having normally closed 55 contacts through which said cut-off relay circuits are completed, electromagnetic mechanism for operating the connector switch elements, a relay which is energized upon the actuation of the operating mechanism 60 to open said closed contacts during the operation of the switching mechanism and a source of current supply for said circuits.

22. In a switching mechanism for telephone exchange service, the combination 65

with a movable element, a motor magnet and means operated thereby for advancing said element progressively, of a circuit for said magnet having normally closed and normally open sets of contacts, a relay 70 controlling the set of closed contacts and another relay controlling the set of open contacts, which responds to impulses of current with less rapidity than the other relay, an operating circuit connected to both relays, 75 means for transmitting impulses of current over said circuit and a source of current supply for said circuits.

23. In a switching mechanism for telephone exchange service, the combination 80 with a movable element, a motor magnet and means operated thereby for advancing said elements successively, of a circuit for said magnet having normally closed and normally open sets of contacts, a relay 85 controlling the set of closed contacts and another relay controlling the set of open contacts which responds to impulses of current with less rapidity than the first mentioned relay, a normally open operating circuit in 90 which both relays are included, means for closing the circuit to transmit a single impulse of current to energize both relays and reverse the positions of the contacts controlled by each, a device in the operating 95 circuit for transmitting subsequent impulses of current to successively close and open the motor magnet circuit and a source of current supply for said circuits.

24. In a telephone exchange system, the 100 combination with a plurality of normally open instrument circuits, a finder switch mechanism and connector switch mechanism for placing one circuit when it is closed in electrical connection with another, of electromagnetic devices for restoring said mechanisms to destroy the connection, an operating circuit therefor which is rendered inoperative during the movements of said mechanisms, means for maintaining said circuit in an inoperative condition during the time two instrument circuits are connected and subsequently rendering it operative when one of said connected instrument circuits is opened and a source of current supply for 115 said circuits.

25. In a telephone exchange system, the combination with a plurality of normally open instrument circuits, finder and connector switch mechanisms comprising terminals for said circuits and movable contact elements coöperating therewith for placing one instrument circuit in electrical connection with another, said finder and connector switches operating successively, the former to pick up a closed circuit, and the latter to connect it with an open circuit, of electromagnetic devices for restoring said switch mechanisms to destroy the connection, means actuated by 130

- the closing of an instrument circuit to render the restoring device of the finder switch inoperative during the movement thereof, other means subsequently actuated
- 5 when the finder switch picks up the line for rendering the restoring devices of both switches inoperative during the time an instrument circuit is closed and a source of current supply for said circuits.
- 10 26. In a telephone exchange system, the combination with a plurality of normally open instrument circuits, finder and connector switching mechanism comprising terminals for said lines and movable contact ele- 70
- 15 ments for placing one instrument circuit in electrical connection with another, said finder and connector switches being adapted to be operated in succession by impulses of current transmitted over one of the instrument cir- 80
- 20 cuits, of electromagnetic devices for restoring said mechanisms to their normal position, a relay associated with the finder switch which is energized when an instrument circuit is closed to render the restoring mechanism of said switch inoperative, another relay energized by current in said closed instrument circuit when the finder switch picks up said circuit, said relay operating to hold the restoring devices of both 85
- 25 switches inoperative while said instrument circuit is retained in an operative closed condition and a source of current supply for 90
- 30 said circuits.
27. In a telephone exchange system, the combination with a switch comprising a terminal, a movable contact element coöperating therewith and mechanism for operating it, of a normally open outgoing instrument circuit leading from the terminal hav- 100
- 35 ing signaling devices therein, an incoming instrument circuit adapted to be connected to the outgoing circuit through said switching mechanism, a normally closed signaling circuit bridged to the outgoing instrument 105
- 40 circuit and a signaling current generator, a relay for breaking the signaling circuit, a relay circuit and means for intermittently supplying current thereto, means actuated when the outgoing circuit is closed for hold- 110
- 45 ing current in the relay circuit and a source of current supply for said instrument circuits.
- 50 28. In a telephone exchange system, the combination with a switch comprising a terminal, a movable contact element coöperating therewith and mechanism for operating it, of a normally open outgoing instrument circuit leading from the terminal having signaling devices thereon, a signaling cur- 115
- 55 rent generator and a source of current pro- 120
- 60 vided for talking purposes, separate circuits leading from said source and generator hav- 125
- 65 ing terminals and contact members arranged in the outgoing instrument circuit and adapted to alternately coöperate with said
- terminals, a relay having an operating circuit receiving current intermittently to alternately reverse the positions of said contact members, means operated when the instrument circuit is closed, for supplying cur- 70
- 75 rent to said relay continuously and an incoming instrument circuit adapted to be connected with the outgoing circuit through said switch.
29. In a telephone exchange system, the combination with an incoming instrument circuit, a plurality of outgoing instrument circuits and a switching mechanism for connecting the incoming circuit with one or another of the outgoing circuits, signaling de- 80
- 85 vices associated with each instrument circuit and means for supplying signaling current to said circuits, of normally closed contacts located in the circuit traversed by the signaling current, a relay associated with the switching mechanism which is energized to open said contacts during the movement of said mechanism to prevent the operation of the signaling devices upon any but the instrument circuit selected by said 90
- 95 switch and a source of current supply for said instrument circuit.
30. In a telephone exchange system, the combination with an incoming instrument circuit, a plurality of outgoing instrument 95
- 100 circuits each having signaling devices, and switching mechanism, for connecting the first mentioned circuit with one or another of the outgoing circuits, comprising terminals for the latter and movable contact ele- 105
- 105 ments coöperating successively therewith and means for applying signaling current to each instrument circuit as the contact elements engage the respective terminals of said circuits, of mechanism for operating 110
- 115 said elements step by step, comprising a motor magnet controlled by current impulses of given frequency, a relay responding to current impulses with less rapidity than the magnet which is retained in energized condition during the transmission of current impulses of regular frequency to said magnet, contacts in the circuit traversed by the signaling current which are opened when the relay is so energized, and a source for 115
- 120 supplying current for talking purposes to supply said instrument circuits.
31. In a telephone exchange system, the combination with a plurality of normally open outgoing instrument circuits, each 120
- 125 comprising a line and a mate conductor and having signaling devices therein, a switching mechanism comprising terminals for said conductors, movable contact elements coöperating therewith and mechanism for operating them, of a line and a mate switch conductor connected to each of said elements having movable contact members therein, a source of current for signaling purposes comprising a circuit having terminals nor- 130

mally engaged by the movable contact members, means for interrupting the flow of signaling current, a source of current for talking purposes comprising a circuit having 5 terminals also coöperating with said members, means actuated when an outgoing instrument circuit is closed for holding the source of talking current applied thereto and an incoming instrument circuit adapted to 10 be connected to one of the outgoing circuits through the switching mechanism.

32. In a telephone exchange system, the combination with a switching mechanism comprising a plurality of terminals and 15 movable contact elements coöperating therewith, outgoing instrument circuits leading from the terminals having signaling devices thereon, an incoming instrument circuit connected with the outgoing circuits 20 through said elements, mechanism for operating the contact elements comprising a controlling relay and an associate relay, both responding to impulses of current in the incoming instrument circuit, of a source of 25 current for signaling purposes comprising a circuit normally bridged to the instrument circuits as the movable elements successively engage their respective terminals, a normally open set of contacts in said signaling 30 circuit adapted to be closed by the aforementioned associate relay, a third relay for cutting off the source of signaling current during the operation of said switching mechanism, said third relay being adapted 35 to respond to impulses of current with less rapidity than the controlling relay and having a circuit which is energized in unison with the controlling relay, when the switching mechanism is in normal position, and is 40 retained in energized condition during the operation of the controlling relay and a source of current supply for said instrument circuits.

33. In a telephone exchange system, the 45 combination with a switching mechanism comprising a plurality of terminals and a movable contact element coöperating therewith, outgoing instrument circuits leading from the terminals having signaling devices 50 therein, an incoming instrument circuit comprising a conductor adapted to be connected to one or another of the outgoing circuits through the movable contact element and mechanism for operating the latter, of controlling devices therefor comprising a controlling relay and an associate relay both 55 responding to impulses of current in the incoming instrument circuit, normally closed contacts in said conductor and a third relay 60 adapted to respond to impulses of current with less rapidity than the controlling relay which is energized to open said contacts and hold them open during the operation of the switching mechanism and subsequently release them, a source of current for signaling 65

purposes comprising a circuit normally completed through said conductor, an additional set of normally open contacts in said conductor normally disconnecting the incoming circuit from a selected outgoing circuit, 70 means for cutting off the signaling current and closing the last mentioned contacts and a source of current supply for said instrument circuits.

34. In a telephone exchange system, the 75 combination with a step-by-step switching mechanism comprising a plurality of terminals and a movable contact element coöperating therewith, outgoing instrument circuits leading from the terminals having 80 signaling devices thereon, an incoming instrument circuit adapted to be connected to one or another of the outgoing circuits comprising a conductor leading to the movable contact element, and mechanism for operating the latter progressively embodying a motor magnet having a circuit provided with two sets of contacts, of devices for controlling its operation comprising two relays both adapted to be energized by impulses 85 of current in the incoming instrument circuit one of said relays being adapted to respond to impulses of current with less rapidity than the other for the purposes of holding one of said sets of contacts closed 90 while the other set is vibrated in unison with impulses of current in the operating circuit of the more rapid relay, a set of normally closed contacts in the conductor, a local relay associated with said rapid relay which is energized simultaneously with the latter to open said contacts and is retained in energized condition during the operation of the motor magnet, a source of current for signaling purposes comprising a 100 circuit normally bridged to the aforementioned conductor, and a source of current supply for the other circuits.

35. In a telephone exchange system, the 105 combination with a step-by-step mechanism comprising a plurality of terminals and a movable contact element coöperating therewith, outgoing instrument circuits leading from the terminals having signaling devices 110 thereon, an incoming instrument circuit adapted to be connected to one or another of the outgoing circuits through the movable contact element comprising a switching conductor and mechanism for operating the latter progressively embodying a motor magnet 115 having a circuit provided with two sets of contacts, of devices for controlling its operation comprising a rapidly operating controlling relay and a relatively slower operating associate relay both responding to 120 impulses of current in the incoming instrument circuit, the slower relay being adapted to hold one set of contacts in the motor magnet circuit closed while the other set of contacts is vibrated in unison with a suc- 125

cession of impulses of current transmitted over the incoming instrument circuit, a set of normally open contacts in the switching conductor, a relay for closing them to establish a line connection between said incoming circuit and one or another of the outgoing circuits, said relay having an operating circuit provided with a set of normally open contacts which are closed by the controlling relay and a set of normally closed contacts, an additional relay which is energized during the operation of the motor magnet to open said set of closed contacts, a source of current for signaling purposes comprising a circuit which is completed through the switching conductor when the aforementioned line contacts therein are open, said signaling circuit having an opening which is closed by the slower associate relay and a source of current supply for the other circuits.

36. In a telephone exchange system, the combination with a switching mechanism comprising a plurality of terminals and a movable contact element coöperating therewith, outgoing instrument circuits leading from the switch terminals, means for operating said element comprising a motor magnet having a circuit provided with normally open and normally closed sets of contacts, a relay controlling the set of closed contacts and a secondary relay adapted to close the set of open contacts in the motor magnet circuit, of circuits for operating said relays, a plurality of incoming instrument circuits, means for connecting one or another of the latter to the relay operating circuits and also connecting it to the movable contact element, devices on each of said instrument circuits for transmitting current impulses thereover to actuate said relays during the selective operation of said movable contact element and a source of current supply for said circuits.

37. In a telephone exchange system, the combination with a switching mechanism comprising a plurality of terminals and a movable contact element coöperating therewith, outgoing instrument circuits leading from the switch terminals, means for operating said element comprising a motor magnet having a circuit provided with normally open and normally closed sets of contacts, a relay controlling the set of closed contacts and a secondary relay adapted to close the set of open contacts in the motor magnet circuit, of circuits for operating said relays, a plurality of normally open incoming instrument circuits, devices operated automatically when one of said circuits is closed for placing it in operative relationship with the relay operating circuits, means for transmitting impulses of current over such circuit to actuate the first mentioned relay successively and retain the secondary relay energized during

the transmission of the impulses and a source of current supply for the other circuits.

38. In a telephone exchange system, the combination with a switching mechanism comprising a plurality of terminals and a movable contact element coöperating therewith, and outgoing instrument circuits leading from the terminals, means for operating the element comprising a motor magnet having a local operating circuit provided with normally open and normally closed sets of contacts, a switch conductor and a plurality of incoming instrument circuits normally disconnected therefrom, of switching mechanism for connecting one or another of the incoming circuits in circuit with said conductor and switch element, a relay arranged in circuit with the conductor which controls the normally closed set of contacts, means for transmitting impulses of current over a circuit so connected to successively open and close said contacts, a secondary relay for closing the normally open set of contacts in the motor magnet circuit, said secondary relay being actuated and retained in actuated condition during the operation of the controlling relay and a source of current supply for said circuits.

39. In a telephone exchange system, the combination with a step-by-step switching mechanism comprising a plurality of terminals and a movable contact element coöperating therewith, and outgoing instrument circuits leading from the terminals, means for operating the element comprising a motor magnet having a local operating circuit provided with normally open and normally closed sets of contacts, a switch conductor and a plurality of normally open incoming instrument circuits which are normally disconnected from the conductor, of switching mechanism for connecting one or another of the incoming circuits with said conductor and the aforementioned switch element when one of said incoming circuits is closed, a relay arranged in circuit with the conductor which is energized by the closed incoming circuit to open the normally closed set of contacts, when the connection with said incoming circuit is established, means for opening and closing said incoming circuit to cause a corresponding opening and closing of the motor magnet circuit, a secondary relay for closing the normally open set of contacts in the motor magnet circuit, the secondary relay being energized simultaneously with and being retained in actuated condition during the operation of the aforementioned relay and a source of current supply for said circuits.

40. In a telephone exchange system, the combination with a plurality of incoming and outgoing instrument circuits, a finder switch for selecting an incoming circuit, and a connector switch for selecting an

outgoing circuit and a tie between the switches for placing the selected instrument circuits in connection, of operating mechanism for the connector switch comprising a motor magnet, a local circuit for said magnet having a set of normally closed contacts and a set of normally open contacts, a relay controlling the normally open set of contacts, a normally open operating circuit therefor bridged to said switch tie and including one of the incoming instrument circuits, when the latter is connected to said tie by the finder switch, means for closing said open operating relay circuit to open the closed set of contacts in the motor magnet circuit, a device for subsequently transmitting impulses of current over said operating circuit, means actuated upon the closing of the latter for closing the normally open set of contacts in said motor magnet circuit and a source of current supply for said circuits.

41. In a telephone exchange system, the combination with a plurality of incoming and outgoing instrument circuits, a finder switch for selecting an incoming circuit, a connector switch for selecting an outgoing circuit and a tie between the switches for connecting the circuits selected by them, of operating mechanism for the connector switch comprising a motor magnet having a local circuit provided with sets of normally closed and normally open contacts, means for closing each incoming instrument circuit and a device for subsequently transmitting impulses of current over each of said circuits, a controlling relay and a secondary relay both adapted to be energized when the finder switch selects a closed incoming circuit, said relays respectively opening and closing the contacts in the motor magnet circuit, the secondary relay operating conjointly with the controlling relay to maintain its set of contacts in the closed position during the subsequent opening and closing of the incoming operating circuit and a source of current supply for said circuits.

42. In a telephone exchange system, the combination with a plurality of incoming and outgoing instrument circuits and finder and connector switching mechanism for respectively selecting a given circuit and connecting it to another and mechanism for operating one of the switches comprising a motor magnet, of two relays having different time constants, each controlling a set of contacts, those of the more rapidly operating relay being normally closed and those of the slower relay being normally open and a circuit for the motor magnet leading through said contacts, local circuit branches for said relays connected by the finder switch with the incoming circuit selected by it, means for sending impulses of current over said

connected instrument circuit and circuit branches and a source of current supply for said circuits.

43. In a telephone exchange system, the combination with a plurality of incoming and outgoing instrument circuits and finder and connector switching mechanisms for respectively selecting a given circuit and connecting it to another, mechanism for operating one of the switches comprising a motor magnet and a circuit therefor having sets of normally closed and normally open contacts, of a relay for closing the latter and a second relay for opening the former set of contacts which latter operates in response to impulses of current with greater rapidity than the former relay, whereby its contacts may be open and closed before the contacts of the other relay can be opened, a local circuit branch for the more rapidly operating relay connected with the incoming circuit selected by the finder switch, a circuit for the slower relay which is energized during the operation of the faster relay, means for sending impulses of current over said connected instrument circuit and circuit branch and a source of current supply for said circuits.

44. In a telephone exchange system, the combination with a plurality of incoming and outgoing instrument circuits and finder and connector switching mechanisms for respectively selecting a given circuit and connecting it to another and mechanism for operating one of the switches comprising a motor magnet, of two relays having different time constants, each controlling different sets of contacts, means for rendering both relays responsive in unison with the first impulse of current on an incoming instrument circuit when it is selected by the finder switch, a local circuit for the motor magnet leading through the sets of contacts of the two relays which is energized in unison with the second and subsequent impulses of current on said selected incoming circuit and a source of current supply for said circuits.

45. In an automatic telephone exchange system, the combination with a plurality of telephone instruments having normally open receiver hook contacts, circuits leading through said contacts and an impulse transmitter also arranged in each circuit and adapted to alternately open and close it and retain said circuit closed on the termination of the impulses thereover, of finder and connector switching mechanisms for respectively selecting a given circuit and connecting it to another, mechanism for operating the connector switch comprising a motor magnet having a circuit provided with two openings, a relay which is connected to one or another of said instrument circuits by the finder switch and energized by impulses of current thereon to open and close one set

of contacts in the circuit of the motor magnet, a second relay for closing the other set of contacts in the last mentioned circuit which operates conjointly with the first relay to close its respective contacts upon the closing of the operating instrument circuit in the first instance and to hold them closed during the transmission of successive impulses of current on said operating circuit 10 and a source of current supply for said circuits.

46. In a telephone exchange system, the combination with a plurality of incoming and outgoing instrument circuits and finder 15 and connector switching mechanisms for respectively selecting a given circuit and connecting it to another, mechanism operating one of the switches comprising a motor magnet and a locking device for securing 20 said switching mechanism in operative position, of a releasing magnet for disengaging it, a circuit for the motor magnet having normally open contacts and a circuit for the release magnet having normally closed contacts, a relay for closing the motor magnet 25 circuit and opening that of the release magnet, said relay being adapted to be energized by current in the instrument circuit which is selected by the finder switch and 30 a source of current supply for said circuits.

47. In a telephone exchange system, the combination with a plurality of normally open instrument circuits and finder and connector switching mechanisms for respectively 35 selecting a given circuit and connecting it to another, mechanism for operating the finder switch which is actuated by closing an instrument circuit, mechanism for operating the connector switch comprising 40 a motor magnet adapted to actuate in unison with impulses of current transmitted over the circuit selected by the finder switch, and a motor magnet circuit having a set of normally open contacts, of locking devices 45 for securing said switching mechanisms in their respective positions of adjustment, releasing magnets for unlocking them, a circuit for said magnets having a set of normally closed contacts, means for closing the 50 motor magnet circuit and opening that of the releasing magnets, which is adapted to be actuated by the closed instrument circuit, selected by the finder switch, to retain the circuit of the releasing magnets in open 55 condition until said closed instrument circuit is subsequently opened and a source of current supply for said circuits.

48. In a telephone exchange system, the combination with a plurality of normally open instrument circuits and finder and connector switching mechanisms for respectively selecting a given circuit and connecting it to another, mechanism for operating the finder switch which is actuated by closing 65 an instrument circuit and mechanism

for operating the connector switch which is actuated by impulses of current in the selected circuit after it has been picked up by the finder switch, of locking devices for the switching mechanisms, releasing magnets 70 for unlocking them, a circuit for said magnets which is open when the switching mechanisms are in their normal position and is closed when one of the mechanisms is operated, a set of closed contacts in said circuit, a relay for opening them which is energized when the finder switch picks up the closed instrument circuit and a source of current supply for said circuits. 75

49. In a telephone exchange system, the combination with a plurality of normally open instrument circuits and finder and connector switching mechanisms for respectively selecting a given circuit and connecting it to another, mechanism for operating 80 the finder switch which is actuated by closing an instrument circuit and mechanism for operating the connector switch which is actuated by impulses of current in the selected circuit after it has been picked up by 85 the finder switch, of separate locking devices for each switching mechanism, separate releasing magnets for unlocking each mechanism and a compound circuit connecting both of said magnets, having two sets of 90 normally closed contacts and two sets of normally open contacts, one of each of the latter being arranged to be closed upon the movement of the finder and connector switching mechanisms, means associated 95 with the finder switch for opening one of the closed contacts during its movement, similar means associated with the connector switch for opening the other set of closed contacts during its movement, and a source 100 of current supply for said circuits.

50. In a telephone exchange system, the combination with a plurality of normally open instrument circuits and finder and connector switching mechanisms for respectively selecting a given circuit and connecting it to another, mechanism for operating the finder switch which is actuated by closing an instrument circuit, mechanism for operating the connector switch which is actuated by impulses of current in the selected circuit after it has been picked up by the finder switch, of locking devices for the switching mechanisms, releasing magnets 110 for disengaging them, a compound circuit 115 for controlling said magnets independently or simultaneously which is normally open when the switching mechanisms are in their normal position and is energized to operate a release magnet when its respective 120 switching mechanism is operated, means for rendering one of said magnets inoperative when the finder switch is started by the closing of an instrument circuit, other means for retaining the aforesaid magnet inopera- 125 130

tive and rendering the other release magnet inoperative when said switch picks up the instrument circuit and a source of current supply for said circuits.

- 5 51. In a telephone exchange system, the combination with a plurality of normally open instrument circuits and finder and connector switching mechanisms respectively selecting a given circuit and connecting it to another, mechanism for operating the finder switch which is actuated by closing an instrument circuit, mechanism for operating the connector which is actuated by impulses of current in the selected circuit after it has 10 been picked up by the finder switch, of locking devices for the switching mechanisms, releasing magnets for disengaging them, a compound circuit for controlling said magnets which is closed when either switching mechanism is adjusted out of its normal position to energize the respective release magnet thereof, means for rendering the finder switch release magnet inoperative when said switch is started by the closing 15 20 25 30 35 40 45 50 55 60 65 70 75 80 85 90 95 100 105 110 115 120 125 130
- of an instrument circuit, other means operated when the finder switch picks up said circuit for rendering the release magnets of both the finder and connector switches inoperative and retaining them in an inoperative condition until the closed instrument circuit is broken and a source of current supply for said circuits.
52. In a telephone exchange system, the combination with a plurality of circuits each 35 provided with a telephone instrument thereon having normally open contacts adapted to be closed when said instrument is in use, a transmitter for each circuit for sending impulses of current thereover and finder 40 and connector switching mechanisms for respectively selecting a given circuit and connecting it to another, operating mechanism for the finder switch which is actuated when an instrument circuit is closed, mechanism for operating the connector switch comprising a motor magnet adapted to operate in unison with current impulses subsequently transmitted thereover after said circuit has been selected by the finder switch, 45 devices for locking the switching mechanisms in operated position and magnets for releasing them, a relay controlling the operation of said magnets which is actuated, when the finder switch picks up a closed instrument circuit, to render them inoperative and subsequently restores them to operative condition when said instrument circuit is opened and a source of current supply for said circuits.
- 60 53. In a telephone exchange system, a plurality of instrument circuits, two switching mechanisms, each comprising terminals to which each of said circuits is connected and movable contact elements coöperating 65 therewith, the corresponding terminals of

each circuit on the separate switches being arranged relatively to each other and to the direction of movement of their respective contact elements so that one of the latter will coöperate with a terminal of a given circuit in advance of the engagement of the corresponding terminal of said circuit on the other switch by the contact element thereof, of means for operating said element of both switches simultaneously.

54. In a telephone exchange system, the combination with two switching mechanisms each comprising a bank of terminals, movable contact elements coöperating therewith and operating devices for advancing the latter in one direction, a plurality of instrument circuits each connected to one of the terminals of each switch, said terminals of each circuit being located in reverse position in its respective bank of terminals relatively to the direction of movement of the contact elements, of means for actuating the operating devices of the two switches simultaneously.

55. In a telephone exchange system, the combination with a plurality of normally open instrument circuits, a plurality of switching mechanisms each comprising terminals for said circuits and movable contact elements coöperating therewith, the corresponding terminals of each instrument circuit being arranged relatively to each other and to the direction of movement of their respective contact elements so that one of the latter will coöperate with a terminal of a given circuit in advance of the engagement of the corresponding terminal of said circuit on the other switch by the contact element thereof, of electromagnetic operating mechanisms for driving the contact elements of each switch which are actuated simultaneously when an instrument circuit is closed, devices for arresting said mechanisms when their respective contact elements engage the terminal of the closed instrument circuit, means for restoring the elements when the latter fail to engage such terminal and a source of current supply for said circuits.

56. In a telephone exchange system, the combination with a plurality of normally open instrument circuits, a plurality of switching mechanisms each comprising terminals for said circuits and movable contact elements coöperating therewith, the corresponding terminals of each instrument circuit being arranged relatively to each other and to the direction of movement of their respective contact elements so that one of the latter will coöperate with a terminal of a given circuit in advance of the engagement of the corresponding terminal of said circuit on the other switch by the contact element thereof, of electromagnetic operating mechanisms for driving the contact elements of each switch which are normally

- inoperative but are adapted to be actuated simultaneously by the closing of an instrument circuit to move the respective switch elements to their limit of movement in one direction, devices for arresting the mechanism of the switch whose element first picks up the terminal of a closed circuit, means for restoring the switch elements which operates automatically to return the non-arrested element when it reaches the limit of its movement and also restores the arrested element upon the opening of the closed instrument circuit and a source of current supply for said circuits.
5. 57. In a telephone exchange system, the combination with two switching mechanisms each comprising a bank of terminals and movable contact elements coöperating therewith, a plurality of normally open instrument circuits each connected to one of the terminals of each switch, said terminals of each circuit being located in reverse position in its respective bank of terminals relatively to the direction of movement of the contact elements, of operating devices adapted to be actuated by the closing of an instrument circuit to progressively advance said contact elements of the two switches over their banks of terminals, means for arresting the operating devices of the two switches which stops the movement of the switch element first engaging the terminal of said closed instrument circuit, mechanism for restoring the elements of both switches which is rendered inoperative in respect to the switch whose element is arrested and is subsequently rendered operative when the closed instrument circuit is opened and a source of current supply for said circuits.
10. 58. In a telephone exchange system, the combination with a plurality of normally open instrument circuits, two switches each comprising terminals for each circuit and movable contact elements coöperating therewith, the corresponding terminals of each switch being located relatively in reverse positions in respect to the direction of movement of their contact elements, an additional terminal on each switch associated with each instrument circuit terminal and circuit branches connecting said additional terminals in pairs, provided with normally closed contacts, of electromagnetic mechanism for driving each switch element progressively comprising an operating circuit, a wiper coöperating with said additional terminals to successively close the operating circuit through said circuit branches and an actuating relay associated with each instrument circuit which is operated when its instrument circuit is closed to open the contacts in its respective operating circuit branch, a cut-off relay controlling each actuating relay to permit said contacts to be closed, a cut-off relay circuit comprising terminals associated with those aforementioned on each switch, a third wiper on each switch coöperating with said cut-off circuit terminals and supplying current thereto, means for actuating both switches when an instrument circuit is closed, arresting devices which stop the movement of the elements of the switch which first engage the terminal of a closed instrument circuit, devices for restoring said elements to their normal position and a source of current supply for said circuits.
15. 59. In a telephone exchange system, the combination with a plurality of normally open instrument circuits, two finder switches and two connector switches, all comprising movable contact elements and terminals for the instrument circuits, with which the contact elements coöperate, the corresponding terminals of each instrument circuit on the finder switches being oppositely arranged relatively to each other and to the direction of movement of their respective contact elements, whereby the elements of one switch will engage the terminal of a given instrument circuit in advance of the engagement of the element of the other finder switch with the corresponding terminal of said circuit, of means for automatically operating the finder switches simultaneously when an instrument circuit is closed and arresting them when their contact elements pick up the terminals of said circuit, electromagnetic mechanism for operating each connector switch which is connected to and placed under the control of the closed instrument circuit by its associate finder switch.
20. 60. In a telephone exchange system, the combination with a plurality of normally open instrument circuits, a plurality of finder switches each comprising terminals for said circuits arranged in banks and movable contact elements coöperating therewith, the corresponding terminals of each instrument circuit on the separate switches being arranged in dissimilar positions in the different banks and means for starting the operation of said switches when an instrument circuit is closed and arresting whichever one of them first engages terminals devoted to said closed circuit, of a connector switch associated with each finder switch also comprising circuit terminals, those of the several connector switches being connected in multiple and electromagnetic operating mechanism for each connector switch which is connected to and placed under the control of the closed instrument circuit by its associate finder switch.
25. 61. In a telephone system, the combination with a plurality of normally open instrument circuits, a branch starting circuit and a branch operating circuit associated with each line, a plurality of finder switches each having terminals for the instrument

circuits and comprising wipers coöperating therewith and mechanism for driving them embodying a motor magnet having a common starting circuit adapted to receive an impulse of current from any of the branch starting circuits and also having a common operating circuit arranged to receive successive impulses of current from the branch operating circuits, of a relay which is energized when an instrument circuit is closed for opening the corresponding branch operating circuit and closing the branch starting circuit, another relay which is energized whenever the wipers of one of the switches engages the terminals of a closed instrument circuit to close the previously open branch operating circuit during the movement of the other switches and release mechanism for each switch which is operated after their wipers have traversed the terminals of all instrument circuits thereon.

62. In a telephone exchange system, the combination with a plurality of normally open telephone instrument line circuits and a switching mechanism comprising terminals for the lines, wipers coöperating therewith and mechanism for driving them, of a motor magnet for operating said mechanism, a starting circuit adapted to receive current whenever an instrument is closed to supply an initial impulse to the motor magnet, a relay also arranged to be energized simultaneously with the motor magnet and adapted to respond to current impulses with less rapidity than the motor magnet, a circuit for said relay receiving current each time the switch wipers are stepped into engagement with terminals of normal or open lines and a motor magnet circuit rendered operative by said relay and means for causing successive impulses of current to traverse said circuit when in operative condition.

63. In a telephone exchange system, the combination with a plurality of normally open telephone instrument line circuits, a branch operating circuit associated with each line, and a switching mechanism comprising terminals for the lines and branch circuits, wipers coöperating therewith and mechanism for driving them; of a motor magnet for operating said mechanism, a starting circuit adapted to receive current whenever an instrument is closed to supply an initial impulse to the motor magnet, a relay also arranged to be energized simultaneously with the motor magnet and adapted to respond to current impulses with less rapidity than the motor magnet, a circuit for said relay including one of the wipers which receives current successively from the branch operating circuits of normal or open lines, and a motor magnet circuit rendered operative by said relay and means for causing successive impulses of current to traverse said circuit when in operative condition.

64. In a telephone exchange system, the combination with a plurality of normally open instrument circuits, a switching mechanism having terminals for each line, wipers and mechanism for driving them, of a motor magnet and a relay associated therewith both adapted to receive an initial impulse of current when an instrument circuit is closed, an operating circuit for the motor magnet having normally open and normally closed sets of contacts so arranged that their conditions are reversed upon the energizing of the magnet and relay, the last mentioned set of contacts being arranged to vibrate to alternately open and close the motor magnet circuit and the first mentioned set being arranged to hold closed while current is retained in the relay and a circuit for supplying current to the latter during the time the switch wipers are advancing over the terminals of open lines.

65. In a telephone exchange system, the combination with a plurality of normally open instrument line circuits, and a branch operating circuit for each, a switching mechanism having terminals for each line and branch circuit, wipers and mechanism for driving them, of a motor magnet and a relay associated therewith both adapted to receive an initial impulse of current when an instrument circuit is closed, an operating circuit for the motor magnet having normally open and normally closed sets of contacts arranged respectively on the relay and magnet and a circuit for the relay supplying the latter with current from the branch operating circuits as the switch wipers traverse the terminals of open lines.

66. In a telephone exchange system, the combination with a plurality of normally open instrument circuits, a switching mechanism comprising line terminals, wipers and spring actuated devices for advancing them, of a motor magnet having an armature for setting said devices in operative position, a relay associated with the magnet, a starting circuit over which said relay and magnet are adapted to receive an initial impulse of current when an instrument circuit is closed, an operating circuit for the motor magnet having a normally closed set of contacts arranged to be opened upon each movement of the motor magnet armature and a set of normally open contacts adapted to be closed when the relay is energized and a circuit supplying current to the relay during the engagement of the switch wipers with open instrument circuits.

67. In a telephone exchange system, the combination of normally open instrument circuits, a switching mechanism comprising line terminals, wipers and spring actuated devices for advancing them, a motor magnet having an armature for setting said devices in operative position, a relay asso-

ciated with said magnet, a starting circuit for supplying an initial impulse of current to the relay when an instrument circuit is closed, said starting circuit including contacts which are open when the switch wipers are advanced from their normal position, an operating circuit for the motor magnet having a normally closed set of contacts arranged to be opened upon each movement 10 of the motor magnet armature, a set of normally open contacts arranged to be closed when the relay is energized, and a circuit supplying current to the relay during the engagement of the switch wipers with the terminals of the open instrument circuits.

68. In a telephone exchange system, the combination with a plurality of normally open instrument circuits, a switching mechanism comprising line terminals, wipers and 20 spring actuated devices for advancing them in one direction and a spring for moving them in the other direction, a locking device holding the wipers in operative position, of a motor magnet having an armature for setting the advancing device in operative position, a release magnet having an armature for tripping the locking device, a relay associated with the motor magnet, both of which are adapted to receive an initial impulse of 30 current when an instrument circuit is closed, an operating circuit for the motor magnet having a normally closed set of contacts arranged to be opened upon each movement of the motor magnet armature and a set of normally open contacts adapted to be closed 35 when the relay is energized and a circuit supplying current to the relay during the engagement of the switch wipers with open instrument circuits, a circuit for the release 40 magnet having two sets of normally closed contacts one of which is opened while said relay is energized and the other set being opened when the switch wipers engage the terminals of a closed line.

69. In a telephone system, incoming lines, outgoing lines having normally closed contacts, an automatic switch for connecting said incoming and said outgoing lines, means for operating said switch, means for releasing said switch, means for opening some of said contacts during the setting of said switch, and means for opening others of said contacts during the release of said switch.

70. In a telephone system, incoming lines, outgoing lines having normally closed contacts, an automatic switch for connecting said incoming and said outgoing lines, means for operating said switch, means for releasing said switch, electromagnets for opening some of said contacts during the setting of said switch, electromagnets for opening others of said contacts during the actuation of said automatic switch, and operating circuits for said electromagnets.

71. In a telephone system, incoming lines, outgoing lines having normally closed contacts, an automatic switch for connecting said incoming and said outgoing lines, means for setting said switch, means for releasing said switch, a relay for opening some of said contacts during the setting of said switch, a slow-releasing relay for opening others of said contacts during the release of said switch, and operating circuits for said relays.

72. In a telephone system, incoming lines, outgoing lines, a switch for interconnecting said lines, means for operating said switch, an electromagnet controlling said operating means, a circuit for said electromagnet, means for releasing said switch, a slow-releasing electromagnet for controlling said release means so connected to said circuit that said electromagnets are simultaneously 85 actuated and a source of talking battery supplied through said slow-releasing electro-magnet.

73. In a telephone system, incoming lines, outgoing lines, a switch for interconnecting said lines, means for operating said switch, an electromagnet controlling said operating means, a circuit for said electromagnet, means for releasing said switch, a slow-releasing electromagnet for controlling said 95 release means connected in series with said electromagnet and a source of talking battery supplied through said slow-releasing electromagnet.

74. In a telephone system, an incoming line, an outgoing line, an automatic switch for interconnecting said lines, a numerical switch in which said outgoing line terminates, means for operating said automatic switch, release mechanism associated with 100 said automatic switch, and means including a slow-releasing relay associated with said numerical switch for directly controlling said release mechanism.

75. In a telephone system, an incoming line, an outgoing line, an automatic switch for interconnecting said lines, a numerical switch in which said outgoing line terminates, means for operating said switches, a release mechanism associated with each of 115 said switches, and means including a slow-releasing relay associated with one of said switches for directly controlling said release mechanisms.

76. In a telephone system, an incoming line, an outgoing line, an automatic switch for interconnecting said lines, a numerical switch in which said outgoing line terminates, means for operating said automatic switch, release mechanism associated with 120 said automatic switch, a slow-releasing relay associated with said numerical switch provided with an armature, and an actuating circuit for said release mechanism having a 125 break point closed at said armature. 130

77. In a telephone system, an incoming line, an outgoing line, an automatic switch for interconnecting said lines, a numerical switch in which said outgoing line terminates, means for operating said switches, a release mechanism associated with each of said switches, a slow-releasing relay associated with said numerical switch provided

with an armature, and actuating circuits for said release mechanism having break points 10 closed at said armature.
